UNITED STATES PATENT OFFICE.

JOHN A. BOYCE, OF SPRINGFIELD, ILLINOIS.

APPARATUS FOR PRINTING AND FOLDING NEWSPAPERS.

1,149,621.

Specification of Letters Patent. Patented Aug. 10, 1915.

Application filed August 19, 1911. Serial No. 645,023.

To all whom it may concern:

Be it known that I, JOHN A. BOYCE, a citizen of the United States, residing at Springfield, in the county of Sangamon and 5 State of Illinois, have invented a new and useful Apparatus for Printing and Folding Newspapers, of which the following is a specification.

This invention relates to printing and 10 folding apparatus.

The general purpose of the invention is to provide in conjunction with full-speed printing mechanisms having plate cylinders two pages in circumference equipped with plates 15 having columns circumferential to the cylinders and adapted to perfect on both sides of a continuously moving web all the main pages and supplement pages of a book-form paper including supplement, or a paper in 20 sections including a supplement by means of one set and the same set of plates at each revolution of the plate cylinders, full-speed main cutting and collecting devices, a full-speed supplement cutter and a former adapted 25 to fold in one paper the page-for-plate matter printed by one set of plates, the sheets running to said former including the one-leaf two page supplement sheet, being invariably printed by one set, and the same 30 set of plates, the mechanism being so constructed and arranged that if one former is used to make the first fold the main cutting and collecting device and the supplement cutting device will preferably run at full 35 speed and always make two cuts for each revolution of the plate cylinders, and all the main cuts and supplement cuts will be assembled before going over the former with the result that it is practicable to always 40 get a paper of the desired number of pages from a single set of stereotype plates, what I mean is, two pages from two plates, four pages from four plates, six pages from six plates, eight pages from eight plates, ten 45 pages from ten plates, twelve pages from twelve plates, fourteen pages from fourteen plates, sixteen pages from sixteen plates, and so on. The old method requires four stereotype plates to print a one-leaf two page 50 sheet; the present new and better way requires only two stereotype plates to print a one-leaf two page sheet for each former in use.

Other purposes are: to provide an apparatus equipped with plate cylinders two pages in circumference adapted to print both

sides of a full-speed web, or webs, in a continuous straight run from start to finish, slit the web or webs before cutting into sheets, cut the web-members into sheets and fold the sheets to produce page-for-plate, book-form papers with supplements, or without supplements, or page-for-plate papers in sections, each paper comprising one section with supplement and another 60 section without supplement; and likewise adapted to print both sides of a continuously moving full-speed web, or webs, a plurality of pages in width, cut the web, or webs, into sheets one-page long and a plurality of pages 65 in width before slitting, slit said plural-page-wide sheets to form two-leaf main sheets and one-leaf supplement sheets and fold said two-leaf sheets with inserted one-leaf sheets to produce page-for-plate book-form papers including supplements, or to produce page-for-plate papers in sections 70 each paper comprising one section with supplement and another section without supplement; the parts being so constructed and 75 arranged that one set, and only one set of plates prints a complete paper at each revolution of the plate cylinders; and to provide in co-operation with plate cylinders two 80 pages in circumference and in width equal 85 to the width of a plurality of pages plus margins and equipped with columns circumferential to the plate cylinders; means for associating the webs printed by the plate cylinders; means for slitting the webs; side-by-side formers or equivalent folders and back-to-back formers or equivalent folders 90 adapted to make the first fold of sheets cut from the webs, or web-members; and means for assembling the first-folded sheets or sections running with their cut edges in the lead and folding the sections together in the second fold; to provide in conjunction with printing means two pages in circumference and in width equal to the width of two pages 95 or a multiple of two pages; means for associating the webs, slitting the webs, cutting the main web-members into two-leaf sheets and the supplement web-member into one-leaf sheets; the mechanisms being in such relation to each other and being timed to operate so that the supplement pages printed by plates occupying one-half-circumference of the supplement printing area will 100 run to one former and supplement sheets 105 printed by plates occupying the other half-circumference of the same supplement print- 110

ing area will run to an opposite former, or to a delivery device in line with the former to which the first named supplement sheet runs.

- 5 The invention contemplates the use of full-speed webs and the mechanism is so constructed and arranged that when using full-speed webs one set of six plates will print a six page paper at each revolution of 10 the plate cylinders, one set of eight plates will print an eight page paper, one set of ten plates will print a ten page paper, one set of twelve plates will print a twelve page paper, and one set of fourteen plates will 15 print a fourteen page paper at each revolution of the plate cylinders, and so on.

The arrangement of the plates on the supplement plate area as hereinafter described, in conjunction with the alternate run of the 20 one-leaf sheets cut from a full-speed supplement web or web-member and in conjunction with means for collecting the two-leaf main sheets before making the first fold, adapts the apparatus to produce papers 25 with supplements, say ten page papers, or fourteen page papers, by means of a less number of plates on the supplement plate cylinders than have heretofore been used to produce the same product.

- 30 The invention primarily contemplates the use of full-speed printing couples a plurality of pages in width, two pages in circumference and equipped with plates having columns circumferential to the plate 35 cylinders; a full-speed secondary cutter making two cuts for each revolution of the plate cylinders; means for leading the cuts from the secondary cutter in the first instance alternately in opposite directions; 40 secondary slitters and switches positioned to coöperate with the secondary cutter; means for causing the cuts initially running divergently from the secondary cutter to change direction and run convergently toward the secondary slitters and switches; a 45 delivery device positioned to coöperate with the secondary slitters and switches and receive discard sheets and a single former, or two opposite formers, positioned to coöperate with the secondary slitters, switches and delivery device. The recited mechanisms disposed in substantially the relation 50 stated, and coöperating as described are effective to produce by means of a less number of decks than have hitherto been used, every product having a multiple of two 55 pages, viz: 4, 6, 8, 10, 12, 14, 16, etc. pages, without skipping any product, that is to say without skipping from an eight-page product 60 up to a twelve-page product, or skipping from a twelve-page to a sixteen-page product, and using only one set, and the same set of plates, for one paper, to print a complete paper at every revolution of the printing 65 couplers; papers having a multiple of

four pages have heretofore been produced without skip, but papers having a multiple of two pages always from one set, and the same set of plates with columns circumferential to the plate cylinders, without skipping any product, have not been produced prior to my invention.

I lay special emphasis on the fact that by using a reduced number of decks, as set forth, to produce a given product, the first 75 cost of the machine capable of producing the product is reduced, the necessary number of stereotyped plates is reduced, the number of attendants necessary to operate the machine is reduced, and the general cost of operation 80 is reduced.

This application relates back to my application #336,856, Apparatus for printing and folding papers, filed October 1, 1906, and upon which U. S. Patent #974,231, was 85 granted to me November 1, 1910.

Under the mode of operation set forth in the present application there is alternate run of the full-speed one-leaf sheets cut from the supplement web, or web-member, and it is 90 therefore practicable to insert every second one-leaf sheet with the two-leaf sheets running from one deck and collected, so that every complete paper may include two collected two-leaf main sheets and a one-leaf 95 insert sheet.

The described arrangement of the plates on the supplement plate cylinders in conjunction with the alternate run of the sheets cut from the supplement web or from the 100 supplement web-member of a composite web, in case the two-leaf main sheets are collected before making the first fold, enables me to produce papers with insert sheets from a less number of plates than have heretofore been 105 used to produce the same product. By a composite web I mean a web comprising the matter of main pages and the matter of supplement pages. If a supplement is required, one deck of either section of the apparatus 110 may be used to print supplement pages exclusively on a one-page-wide supplement web, or web-member, or on a two-page-wide supplement web, or web-member, or may be used to print supplement pages on a one-page-wide member or a two-page-wide 115 member of a composite web; or may be used to print pairs of supplement pages alternating with pairs of main pages on a two-page-wide member of a composite web. The 120 composite web may be two pages wide and have on each side a pair of main pages alternating with a pair of supplement pages, as shown in Fig. 24; or may be three pages wide and have on each side of the web a 125 single row of supplement pages and a double row of main pages as shown in Fig. 23; or may be four pages wide and have on each side of the web a double row of main pages and a double row comprising alternate pairs 130

of supplement pages and main pages as shown in Fig. 25.

The prior practice has been to use one pair of plate cylinders a plurality of pages in width and two pages in circumference and equipped with plates occupying the width of one page on the plate cylinders and operating at half-speed to print supplement pages exclusively; the product being two

- 10 two-page supplement sheets for each revolution of the printing couples. I utilize one pair of plate cylinders two pages in circumference and a plurality of pages in width operating at full-speed, to print on one web
- 15 the matter of two two-page supplement sheets and the matter of one or more two-leaf, four-page main sheets at each revolution of the full-speed printing couples. Under the old practice the two two-page sup-
- 20 pliment sheets printed by the plates occupying part of the width of and extending around the plate cylinders are successively inserted at half-speed with the main sheets of two papers running in succession to the
- 25 same folder. Under the new and better practice the supplement sheets run at full-speed and one two-page supplement sheet is inserted with the two-leaf main sheet or sheets running to one folder and forming
- 30 part of one paper and the other two-page supplement sheet may be inserted with the two-leaf sheet or sheets going to another folder and forming part of another paper, or may be discarded and dropped on to the
- 35 delivery device.

In the art as practised prior to my invention, it has been common to print by means of twelve plates mounted on two plate cylinders two pages in circumference and constituting two sets of plates with six plates in each set, two six-page papers for each revolution of the printing couples, but it has not been possible under the old method to produce at each revolution of the printing couples one six-page paper from one set of six stereotype plates carried on two plate cylinders. Similarly it has hitherto been possible to produce two tens at each revolution of the plate cylinders by means of two sets of plates carried on two plate cylinders and each set comprising ten plates. I am the first to produce ten pages from one set of ten plates on two plate cylinders operating on a full-speed web to print a complete paper at each revolution of the plate cylinders; or to produce fourteen pages from one set of fourteen plates, or eighteen pages from one set of eighteen plates, and so on, operating on full-speed web to produce a complete paper at every revolution of the printing couples.

Another valuable feature of the present invention is, that operating one deck and using a full-speed composite web it is practicable to produce ten-page papers printed

by ten plates when the sheets are collected above the formers.

I am aware that a full-speed composite web has heretofore been used with plate cylinders two plates in circumference and having columns circumferential to the plate cylinders to produce book-form papers comprising collected sheets with two insert sheets in every paper, but if a composite web is used in that way it is impossible to produce a ten-page paper from ten plates on one deck of the printing mechanism.

The drawings are mainly in the nature of diagrams illustrating the relation of the mechanisms and the modes of operation. Cylinders are represented by circles; gears are represented by the pitch lines of the gears, and formers, slitters, cutters, tapes, and minor details are shown conventionally. In case specific constructions are not shown it is to be understood that the constructions are such as are commonly used for the purpose described.

In order to clearly set forth the relation and co-operation of the different mechanisms comprised in the apparatus as a whole it is necessary to treat the several printing mechanisms, cutter mechanisms and folder mechanisms of the double-ender apparatus, as separate units and to this end the reference characters designating like parts in the several views have exponents, prime ('), second (''), third ('''), α , γ , etc. to distinguish one from the other. That part of the apparatus including the left hand printing couples of all the decks and the left hand cutter and folder mechanisms will be designated as the left hand section of the apparatus; and that part of the apparatus including all the right hand cutter and folder mechanisms will be designated as the right hand section of the apparatus.

Figure 1 is a diagrammatic side elevation of a double ender apparatus five decks high, four pages wide, and having plate cylinders two pages in circumference equipped with plates having columns circumferential to the plate cylinders. Fig. 2 is a diagrammatic elevation of the trains of gears operating the printing, web-propelling, cutting, slitting and folding mechanisms. Fig. 3 is a diagrammatic top plan of the apparatus. Fig. 4 is an enlarged side elevation of the upper central part of the apparatus and shows the formers and the mechanisms above the formers. Fig. 5 is an enlarged vertical section on the line X-X. of Fig. 1. Fig. 6 is an enlarged top plan of the mechanism below the horizontal plane of the line Y-Y. of Fig. 1. Figs. 7 and 8 are respectively an enlarged end elevation and an enlarged partial top plan of the secondary cutter. Fig. 9 is a diagram illustrating a mode of operation of the mechanisms shown in Figs. 7 and 8. Fig. 10 is an enlarged

front elevation of one slitter device. Fig. 11 is a vertical section on the line Z.Z. of Fig. 10. Fig. 12 is an enlarged detail of one set of switches. Figs. 13, 14 and 15 are diagrams illustrating different settings of the switches. Fig. 16 is a diagrammatic top plan of the carrier cylinders and the trains of gears below the horizontal plane of the line W. W. of Fig. 1. Figs. 17 and 18 are respectively an enlarged side elevation and top plan of the train of gears actuating the secondary cutter at half-speed or optionally at full-speed. Fig. 19 is a vertical section on the line V. V. of Fig. 17. Fig. 20 is an enlarged isometric view of one of the switches used between the carrier cylinders below the formers. Fig. 21 is an enlarged isometric view of a combined switch and stripper coöperating with the carrier cylinders below the formers. Figs. 22, 23, 24, and 25 are diagrams illustrating the arrangement of the pages on the main and composite webs. Figs. 26 to 35, inclusive, are diagrams illustrating different runs of the webs and sheets. Figs. 36 and 37 are respectively an enlarged end elevation and a partial top plan of one main cutting and collecting unit. Fig. 38 is a diagram showing the setting of the switches above the formers and the position of the effective slitters, when the mechanism is being operated to slit a two-page-wide supplement sheet into two one-leaf sheets, and cause one one-leaf sheet to run to one former in position for insertion with two-leaf main sheets running on the former, and the companion one-leaf sheet to drop onto the central delivery device between the formers. Fig. 39 is a vertical section on the line V. V. of Fig. 38. Fig. 40 is a vertical section on the line S. S. of Fig. 38. Fig. 41 is an enlarged side elevation of one carrier cylinder and appurtenances. Fig. 42 is a vertical section on the line T. T. of Fig. 41, and Fig. 43 is a vertical section on the line P. P. of Fig. 41.

Similar reference characters designate like parts in all the views.

Printing mechanism.—The main frame 1 supports the revoluble plate cylinders 2, 2^a, 2^b, 2^c, 2^d, 2^e, etc.; the revoluble blanket cylinders 3, 3^a, 3^b, 3^c, 3^d, 3^e, etc.; and the paper rolls R. The plate cylinders are two-pages in circumference and four pages wide and are equipped with plates having 55 columns circumferential to the plate cylinders.

Motors and gears.—Twin motors 30 and 30' of suitable construction are adapted to operate separately or together to drive the 60 trains of gears to operate the printing mechanisms synchronously. Spur wheels 31 and 31' secured on the motor shafts mesh with an intermediate gear wheel 32. The motors rotate in the same direction and will 65 both operate to rotate the wheel 32. Either

motor may be used alone to drive all the printing mechanisms by disconnecting the spur wheel 31 or 31' as the case may be. A spur wheel 33 is secured on the shaft of the wheel 32 and turns with the shaft. Spur 70 wheels 35 and 35' (Figs. 2 and 16) are secured on the transverse shafts 40 and 40' by set screws 40^a and 40'^a respectively. By loosening the set screws the wheels may be slid on the shafts. The wheel 33 meshes 75 with and drives the wheel 35'. An intermediate spur gear 34 meshes with the wheels 33 and 35. Intermediate spur gears 36 and 37 driven by the wheel 35 actuate the wheels 38, and similar wheels 36' and 37' driven 80 by the wheel 35' actuate the wheels 38'. The intermediate gear 37 is adapted to slide outward on its spindle 37^a to throw out of gear the printing mechanisms of the left hand section of the machine and the gear 85 37' is adapted to slide outward on its spindle 37'^a to throw out of gear the printing mechanisms of the right hand section of the machine. Internmeshing spur gears 38 (Fig. 2) are secured on the shaft of the plate 90 cylinders 2 and blanket cylinders 3 and similar gears 38' are secured on the shafts of the plate cylinders 2' and the blanket cylinders 3'. Intermediate gears 39 connect the gears 38 of the different decks of 95 the left hand section of the apparatus and similar gear wheels 39' connect the wheels 38' of the different decks of the right hand section of the apparatus.

One deck of each set of printing mechanisms, preferably the upper deck, may be caused to operate at half speed by means of changeable gears 38^a and 39^a of any usual or approved construction.

Bevel gear wheels 41 and 41' are secured 105 on the revoluble horizontal shafts 40 and 40' respectively and mesh with and drive bevel gears 43 and 43' secured on revoluble vertical shafts 42 and 42' respectively. The vertical shafts 42 and 42' are geared as hereinafter described to actuate the cutting, slitting and folding mechanisms.

Associating, slitting and forwarding.—Some or all of the webs perfected by the printing mechanisms of the left-hand section of the apparatus may be associated on the associating and web-propelling roller 24^a and slitted by the slitters 24 to divide the web, or webs, into web-members, and some or all of the webs perfected by the 110 printing mechanisms of the right-hand section of the apparatus may be associated on the roller 24' and slitted by the slitters 24'. An associating and web-propelling roller 9 and slitters 9^a are intermediate of the rollers 24^a and 24'. The slitters 9^a slit lengthwise the web, or webs, or web-members running on the roller 9. The slitters 24, 9^a, 24', etc. are adapted to slit the webs before they are 125 cut into sheets and the slitters 90, 90^a, 90^b, 130

90', 90^a' and 90^b' hereinafter described are adapted to slit the plural-page-wide sheets running from the cylinders 7 and 7' to divide them into sheets one page long and two 5 pages wide or one page long and one page wide, at the option of the user.

Pipe rollers 72, 73, 73', 74, and 74' support the moving webs and admit of associating on the rollers 24^a or 24^a', or 9, as the 10 case may be, some or all of the webs perfected by the printing mechanisms of both sections, or either section of the apparatus. The slitters are hereinafter described in detail.

15. *Secondary cutter.*—Full-width cylinders 4 and 5 (Figs. 1, 4 and 7) are mounted to rotate in suitable bearings on the main frame and are geared to operate at full-speed, or optionally at half-speed and are 20 adapted to make one cut for each half-revolution of the plate cylinders, to cut into sheets in length equal to the length of one page plus margins and in width equal to the width of one or more pages, a web 25 or web-member, or a plurality of webs or web-members running to the cylinders.

For convenience in description the co-operating cylinders 4 and 5 taken together are designated as the secondary cutter. The 30 secondary cutter is preferably central with respect to the main cutters and the formers and is equipped with pins and strippers and is adapted to cut two-leaf main sheets from a main web, a plurality of pages in 35 width or to cut one-leaf supplement sheets from a web or web-member one-page in width or to cut two-leaf main sheets and one-leaf supplement sheet from a composite web or web-member a plurality of pages in 40 width, as will hereinafter appear.

A radial blade 4^c (Figs. 7 and 8) extends the full length of the cylinder 4. An oscillative shaft 4^a extends through the cylinder and a set of pins 4^b are mounted on the 45 shaft. A slotted arm 4^d is secured on the shaft 4^a. An angular arm 4^p is mounted to oscillate on a pivot 4^f on the end of the cylinder 4. The shorter member of the arm 4^p is connected with the arm 4^d by a pin 50 fitting in the slot of the arm 4^d. A roller 4^e is mounted to rotate on the longer member of the arm 4^p. A rod 4^g connected with the arm 4^p slides in a hole in a bracket 4^f on the end of the cylinder 4. A spring 4^h surrounds the rod 4^g and acts to normally keep the arm 4^p in the position shown. An arcuate plate 4^k is secured on the main frame adjacent to one end of the cylinder 4 in such 55 position that when the plate 5^t or 5^v, as the case may be, engages on the roller 4^e during the rotation of the cylinders 4 and 5 it will cause the arm 4^p to turn on its pivot in the direction indicated by the arrow 4^x thereby causing the arm 4^p to occupy such a position 60 that the roller 4^e will roll on the inner sur-

face of the plate 4^k and the inner end of the arm 4^p will act on the arm 4^d to oscillate the shaft 4^a to cause the set of pins 4^b to project through the holes 4^s (Fig. 8) while the roller 4^e is running in contact with the 70 inner surface of the plate 4^k, and when the roller runs off the plate the spring 4^h will immediately act on the arm 4^p to cause retraction of the set of pins. When the plates 5^t and 5^v are not in use the little roller 4^e 75 will normally travel on the outer surface of the arcuate plate 4^k and the pins 4^b will be retracted and ineffective. The cylinder 5 has diametrically opposite cutting-woods 5^c spaced to coöperate with the blades 4^c respectively and having suitably spaced holes 5^{c'} accommodating pins 5^b and holes 5^{c''} accommodating the projecting ends of the pins 4^b during the time that the blades 4^c are cutting the webs on the cutting-woods 5^c. The 80 cylinder 5 is equipped with oscillative shafts 5^a, sets of pins 5^b, arms 5^d and 5ⁿ adjustable on the shafts 5^a, little rollers 5^e mounted on the arms 5^d, brackets 5^f, rods 5^g, connected with the arms 5^d and springs 5^h. 85

A stationary circular plate 5^k having its center in the extended axis of the cylinder 5 has an integral raised cam 5^v half the thickness of the plate. Set screws 5^m connect the arms 5^d with the shafts 5^a so that 90 by loosening the set screws the arms 5^d may be placed in such position on the shafts that the rollers 5^e will run entirely around the circumference of the plate 5^k or will run on the face of the cam 5^v and when the arms 100 are properly placed they may be secured by tightening the set screws. Set screws 5^{m'} connect the arms 5^d with the shafts 5^a so that the arms may be adjusted on the shafts to regulate the scope of movement of the 105 sets of pins 5^b.

During the time that the rollers 5^e are running entirely around the circumference of the plate 5^k the sets of pins 5^b will be retracted, and during the time that the rollers 5^e are running on the cam 5^v the set of pins 5^b actuated by the arm on which the roller is mounted will be projected and effective while the roller is running on the high part of the cam. 110

The arms 5^d may be adjusted so that the rollers 5^e on either arm or both arms will run on the circumference of the plate during the entire rotation of the cylinder; or may be so adjusted that the roller 5^e on either arm, or both arms, will run on the high part of the cam 5^v during partial rotation of the cylinder and on part of the circumference of the plate 5^k during the partial rotation of the cylinder. If the roller travels on the circumference of the plate during the entire rotation of the cylinder the set of pins actuated by the arm on which the roller is mounted will be ineffective during the complete rotation of the cylinder. 115 120 125 130 135

and if the roller travels on the cam the set of pins actuated by the arm on which the roller is mounted will be projected and effective while the roller is running on the high part of the cam and will be retracted and ineffective while the roller is running on the circular part of the plate.

- Flat segmental plates 5^t and $5^{t'}$ having slots 5^{t3} and rounded ends 5^{t2} are connected with the end of the cylinder 5, diametrically opposite to each other and in the plane of the roller 4^e , by bolts 5^{t4} extending through the slots. By loosening the nuts the plates may be slid radially inward on the bolts. The parts are so constructed and arranged that when both plates are in their outward or projected position the plates will engage the roller 4^e twice during the rotation of the cylinders and when the plates are in their retracted position they will pass the roller 4^e without engaging thereon. The plates are separately adjustable so that either plate or both plates may be effective at the option of the user. Each time that a plate 5^t , or $5^{t'}$, engages the roller 4^e it will cause the arm 4^p to turn on its pivot in the direction indicated by the arrow 4^x and thereby cause the set of pins 4^b to become effective as already described. When both plates 5^t and $5^{t'}$ are projected the set of pins 4^b will be twice effective during each rotation of the cylinder 4 and all the cuts will therefore be carried on the cylinder 4. If both plates 5^t and $5^{t'}$ are effective they will act alternately on the little roller 4^e to cause projection of the set of pins 4^b and the set of pins 4^b will hold the leading end of the web upon the cylinder 4 until it is stripped therefrom by the strippers 76^a and upon being stripped from the cylinder the cut sheets will fall on the tapes 75 and be carried downward thereon under the strippers 76^a during the time that the cylinder 4 is completing its revolution and all the cuts will be carried downward on the tapes 75 so long as both plates 5^t and $5^{t'}$ remain effective. If only one plate 5^t , or $5^{t'}$ is effective the set of pins 4^b of the cylinder 4 will be effective once during each revolution of the cylinder 5, and since the cylinder 4 makes two revolutions for each revolution of the cylinder 5 the set of pins 4^b will be effective during one revolution of the cylinder 4 and ineffective during the next revolution of the cylinder 4 and in that case the leading end of the web will be alternately carried around on the cylinders 4 and 5 as will now be described.
- When the web is to be carried on the cylinder 4 the set of pins 4^b must hold the leading end of the web and when the web is to be carried around on the cylinder 5, one set of pins 5^b must hold the leading end of the web. If the web is to run always on the cylinder 4 the set of pins 4^b must be constantly effective to hold the leading end of the web

on that cylinder; if the web is to run always on the cylinder 5 both sets of pins 5^b must be constantly effective to hold the leading end of the web on the cylinder 5; and if the web is to run alternately on the cylinders 4 and 5 one set of pins 4^b and one set of pins 5^b must be alternately effective to hold the leading end of the web first on one cylinder and then on the other.

When one of the plates 5^t , or $5^{t'}$ is in use the adjacent set of pins 5^b must be in disuse, for the reason that the plate 5^t (or $5^{t'}$) in use causes the projecting of the set of pins 4^b and if the set of pins 5^b adjacent to the effective plate 5^t , or $5^{t'}$ were also in use there would be two sets of pins engaging the web at the same time and neither set would be effective for controlling the run of the web.

I will now describe the means for making both sets of pins 5^b effective, the means for making one set effective and the other set ineffective and the means for making both sets ineffective. When the arms 5^n are set on the shafts 5^a respectively in the position shown in Fig. 7 both of the rollers 5^e will run on the surface of the cam 5^k , one roller being on the high part of the cam while the other is on the low part. The rollers 5^e are held against the cam by the springs 5^h acting on the arms 5^d . During the travel of the rollers 5^e respectively the high part of the cam 5^k will cause each arm 5^n in succession to turn outwardly thereby turning the shafts 5^a in succession so as to cause alternate projecting of the sets of pins 5^b and the pins will remain projected and effective as long as the rollers 5^e continue to run upon the high part of the cam and when the rollers run on the low part of the cam the arms 5^n will move inward and thereby turn the shafts 5^a to cause alternate retraction of the sets of pins 5^b through the holes 5^c and the sets of pins will continue retracted and ineffective so long as the rollers continue to run on the low part of the cam. The diameter of the plate 5^k is the same as the diameter of the low part of the cam $5^k'$. If the arms 5^n be slid inward and set in such position that the rollers 5^e will run on the circumference of the plate 5^k and will be held in constant contact therewith by the springs 5^h both sets of pins 5^b will be retracted and ineffective so long as the rollers continue to run on the circumference of the plate 5^k . If one of the arms 5^n is set so that its roller 5^e will run on the circumference of the circular plate 5^k and the other arm 5^n is set so that its roller 5^e will run on the cam $5^k'$ the set of pins actuated by the first named arm 5^n will remain constantly retracted and ineffective and the set of pins actuated by the last named arm 5^n will be alternately effective and ineffective.

From the foregoing it will be seen that

when both sets of pins 5^b are effective both plates 5^t and 5^{t'} and the sets of pins 4^b controlled thereby will be ineffective and the leading end of the web will be held only by 5 the sets of pins 5^b. If one set of pins 5^b is effective and the other set is ineffective the plate 5^t (or 5^{t'}) adjacent to the effective set of pins will be retracted and in disuse and the plate adjacent to the ineffective set 10 of pins will be projected and effective to control the action of the pins 4^b of the cylinder 4 and the leading end of the web passing between the cylinders 4 and 5 will be alternately held by the set of pins 4^b and 15 one set of pins 5^b on the cylinders 4 and 5 respectively; and if both sets of pins 5^b are ineffective both plates 5^t and 5^{t'} will be projected and effective to bring into action the set of pins 4^b and the leading end of the 20 web will be constantly held by the pins 4^b on the cylinder 4 and will not be caught and held by the pins 5^b on the cylinder 5. This construction and arrangement of the mechanisms admits of running all the cuts to 25 the right on the tapes 75' or running all the cuts to the left on the tapes 75 or running the cuts alternately to the right and left on the sets of tapes 75' and 75 respectively and also admits of the use of a full- 30 speed full-width supplement web or composite web or webs run to the secondary cutter and cut into sheets one page in length and one or more pages in width, one cut being made for each half-revolution of the 35 plate cylinders.

Pinch wheels and slitters.—The sets of pinch wheels and slitters used in this apparatus and shown in detail in Figs. 10 and 11 are all substantially alike so a description of one set will suffice for all. The slitter roller 9 turns in suitable bearings on the main frame. A disk 9^a having a knife edge turns in the forks of an arm 9^d which may be turned and set in different positions 45 on the stationary shaft 9^c parallel to the roller 9. An arm 9^e is adapted to turn on the shaft 9^c. A collar 9^g may be slid and turned on the shaft 9^c and may be secured in different positions on the shaft to control 50 the tension of the spring 9^h. A spring 9^b surrounds the shaft 9^c and one end of the spring is connected with the collar 9^g and the other end is connected with the arm 9^e in such manner that the spring acts 55 to turn the arm downward and the torsion of the spring may be changed by changing the setting of the collar 9^g. Forked plates 9^d are longitudinally adjustable on the arm 9^e. Pinch wheels 9^e turn in the forks of 60 the plates 9^d and run in contact with the circumference of the roller 9.

In practice the webs to be slit run on the roller 9 and under the wheels 9^e and the pressure of the wheels on the web may be controlled by setting the collar 9^g to give

to the spring 9^h the torsion necessary for the desired pressure and the arm 9^d may in like manner be set in position most convenient for slitting the webs running on the 70 roller 9. The slitters are adjustable lengthwise of the shaft 9^c and may be placed in position to slit the web into two-page-wide web-members or one-page-wide web-members, at the option of the user.

Strippers and leaders.—When the secondary cutter is operating to cut a web, or web-member, or a plurality of webs, or web-members into sheets as described it is necessary to control the run of the cuts. This is effected by means which will now be described. Oppositely inclined sets of tapes 75 and 75' (Fig. 4) run on rotating rollers 75^a, 75^b, 75^{a'} and 75^{b'}. A shield 77 of any approved construction is below and adjacent the cylinder 5. Strippers 76^a of any approved construction, strip the cuts from the cylinder 4 and the cuts run downward on the tapes 75. Strippers 76^{a'} of approved construction strip the cuts from the cylinder 5 and the cuts run downward on the 90 tapes 75'. The shield 77 supports the free end of the cuts running around the cylinder 5 so that the cuts will not fall away from the cylinder. If the set of pins 4^b is constantly effective all the cuts will run 95 downward on the tapes 75. If the set of pins 4^b and one sets of pins 5^b are effective the cuts will run alternately downward on the tapes 75 and 75', and if both sets of pins 5^b are effective all the cuts will run downward on the tapes 75'. 100

Main cutting and collecting units.—There are two parallel and opposite full-width full-speed main cutting and collecting units (Figs. 4, 36 and 37) one on each side of 105 the secondary cutter. Cuts from the secondary cutter carried by the right hand set of tapes 75' run to the right hand cutting and collecting unit and cuts from the secondary cutter carried by the left hand set 110 of tapes 75 run to the left hand cutting and collecting unit. The left hand cutting and collecting unit comprises the co-acting cylinders 6 and 7 and appurtenances; and the right hand cutting and collecting units 115 comprise the co-acting cylinders 6' and 7' and appurtenances. The main cutting and collecting units may be operated simultaneously and synchronously, or either one may be operated independently of the other. Both main cutting and collecting units are exactly alike so a description of one will suffice for both.

The cylinder 6 has a cutter blade 6^c extending the full length of the cylinder. A 120 shaft 6^a extends the full length of the cylinder and supports a set of pins 6^b. An arm 6^d is secured on the shaft 6^a. An angular arm 6^e is mounted to oscillate on one end 125 of the cylinder and has a slot and pin con-

nexion with the arm 6^a. A roller 6^e is mounted to rotate on the arm 6^p. A guide rod 6^g connected with the arm 6^p slides in a bracket 6^f. A spring 6^h surrounds the rod 6^g 5 and acts on the arm 6^p. An arcuate plate 6^k is secured on the main frame adjacent to one end of the cylinder. The cylinder 7 has diametrically opposite cutting-woods 7^a. The cutting-woods have holes 7^c accommodating the pins 7^d and holes 7^c receiving the ends of the projected pins 6^b. Diametrically opposite shafts 7^a extend through the cylinder and are mounted to oscillate in bearings in the cylinder. Sets of pins 7^b 10 are mounted on the shafts 7^a respectively. Relatively short arms 7^d are connected with the shafts 7^a by set screws 7^m. Longer arms 7ⁿ are connected with the shafts 7^a respectively by set screws 7^m. By loosening the 15 set screws 7^m the arms 7ⁿ may be placed in different positions on the shafts and the set screws may be tightened to keep them in place. Rollers 7^e are mounted to rotate on the arms 7ⁿ. Rods 7^g connected with the 20 arms 7^d extend through stationary brackets 7^f. Springs 7^h surround the rods 7^g and act on the arms 7^d.

A circular plate 7^k is secured on the main frame with its center in the line of the extended axis of the cylinder 7 and has an 25 integral cam 7^k. Diametrically opposite segmental plates 7^t and 7^v are radially adjustable on the cylinder 7 the same as the plates 5^t and 5^v are adjustable on the cylinder 5.

The cutter blade, the set of pins and the pin-actuating and controlling means of the cylinder 7 are exactly like corresponding parts of the cylinder 4; and the cutting- 30 woods, the pins, the pin-controlling means, the cam and the segmental plates pertaining to the cylinder 7 are like corresponding parts of the cylinder 5. The cylinder 6 cooperates with the cylinder 7 in the same 35 manner that the cylinder 4 cooperates with the cylinder 5. Strippers 80, of any approved construction, serve to strip the sheets from the cylinder 7.

If the cutting and collecting unit be used 40 only for cutting, the segmental plates 7^t and 7^v will be adjusted in their retracted position, so that they will not engage the roller 6^e, and in consequence the set of pins 6^b will be retracted and ineffective and the 45 sets of pins 7^b will be projected and effective so that the successive cuts will all run on the cylinder 7. At each rotation of the cylinders 6 and 7 the main webs running thereon will be cut into sheets in length equal to 50 the length of one page plus margins and in width equal to the width of two pages plus margins, or a multiple of two pages plus margins. When collecting, one plate 7^t or 55 7^v as the case may be, will be projected and the other plate will be retracted. When not

collecting, both plates 7^t and 7^v will be retracted.

If it be desired to collect the cut sheets one of the segmental plates 7^t will be set in its projected position and the other will 70 be set in its retracted position so that the parts will coöperate to cause the set of pins 6^b to seize the leading end of the web and hold it on the cylinder 6 during the first 75 rotation of the cylinder and upon the second revolution of the cylinder 6, the complementary set of pins 7^b on the cylinder 7 will seize the leading end of the web, the second sheet will be cut off and the two sheets together will run on the cylinder 7 until they 80 are stripped therefrom by the strippers 80, and after being stripped from the cylinder 7 will run downward over the formers.

The slitters 24, or 9^a or 24', may be used to slit the main webs running to either or 85 both main cutting and collecting units. The full-width full-speed webs may be cut into sheets one-page long and a plurality of pages in width by the main cutting and collecting units, or either of them, and said one 90 page-long sheets may be slit after cutting, to form main sheets one page long and two pages wide, or insert sheets one page long and two pages wide, or one-leaf supplement sheets one page long and one page 95 wide, as hereinafter set forth.

Formers and sheet-propelling devices.—There are four two-page-wide formers 12, 12^a, 12' and 12' (Figs. 1, 2, 4 and 6). The formers have elongated noses 12^x which are 100 effective to crease the sheets gradually thereby avoiding the tearing of the sheets which is likely to result from too sudden creasing. The side-by-side formers 12 and 12^a constitute a pair adjacent to the cylinder 7 and 105 the side-by-side formers 12' and 12'^a constitute a pair adjacent to the cylinder 7'. The formers of the left hand pair incline to the left and the formers of the right hand pair incline to the right. The position 110 of the formers relative to each other and relative to the main cutting and collecting units admits of running the cuts from the left hand main cutting and collecting unit to the left hand formers and from the right 115 hand unit to the right hand formers, or running the cuts from the right hand unit to the left hand formers, or running the cuts from the left hand unit to the right hand formers, or running the cuts from both units to the 120 left hand formers or the right hand formers at the option of the user. The location of the pairs of side-by-side formers positioned to coöperate with second folders as herein-after described, adapts the apparatus to produce papers in sections, one section with an insert sheet and the other without an insert sheet, or to produce papers in sections with an insert sheet in each section, and the sections may be assembled and folded together 125 130

in the second fold to produce a single second-folded paper comprising the entire product of all the printing couples.

Rollers 8 and 8^a are below and parallel to the cylinder 7 and rotate at the same surface speed. Similar rollers 8 and 8^a are below and parallel to and rotate at the surface speed of the cylinder 7'. Parallel full-width cylinders 64 and 64^a are below and intermediate of the cylinders 7 and 7' and rotate at the same surface speed. The cylinders 64 and 64^a have circumferential channels 64^b accommodating the points of the switches which co-operate with the cylinders.

Slitter disks 90, 90', 90^a, 90^{a'}, 90^b and 90^{b'} (Figs. 38-40) are mounted on parallel stationary horizontal shafts 9^c. The slitters 90, 90', etc., and the co-operating strippers 80 are movably connected with the shafts 9^c by set screws 9^c. The slitters cut on the cylinders 64 and 64^a. By loosening the set screws 9^c the slitters and strippers may be adjusted relative to the cylinders and when properly adjusted the set screws 9^c may be tightened to keep the parts in adjustment. This adjustment admits of using one or more of the slitters at the option of the user. The points of the strippers 80 run in circumferential grooves 80' in the cylinders 7 and 7'. The set screws 9^c serve to adjust the strippers 80 relative to the cylinders 7 and 7'.

Tape wheels 13 respectively adjacent to the upper part of the noses of the formers 12 and 12^a carry tapes 14 which run around the rollers 8, 8^a, and the cylinder 64 and guide the central part of the sheets running downward over the formers. Similar tape wheels 13' adjacent to the noses of the formers 12' and 12^{a'} run around the rollers 8', 8^{a'}, and the cylinder 64^a and guide the central part of the sheets running downward over the formers 12' and 12^{a'}. Revolvable rollers 17 and 18 are adjacent and parallel to the sides of the noses of the respective formers. Tapes 15 running on the rollers 8, 8^a, and 9, and 17 cause the sheets to hug the sides of the formers so that the sheets will be perfectly controlled and centrally creased and folded during their run downward along the formers and similar tapes 15' run around the rollers 8', 8^{a'}, 9' and 17' and control and crease the sheets running on the formers 12' and 12^{a'}.

Gears actuating the cutting and collecting mechanisms.—Bevel cog wheels 44, 44' (Figs. 2 and 3) secured on the upper ends of the shafts 42, 42' mesh with and drive combined bevel-cog-pinion-and-spur wheels 45, 45' mounted on the shafts 45^a, 45^{a'} respectively.

Spur wheels 48 and 50 are secured on the shafts of the cylinders 6 and 7 respectively and similar wheels 48' and 50' are secured

on the shafts of the cylinders 6' and 7' respectively. A pinion 51 on the shaft of the cylinder 64^a meshes with and is driven by the wheel 50' and drives the pinion 52 which is secured on the shaft of the cylinder 64. Spur wheels 54 and 55, shown in enlarged detail in Figs. 17-19 are secured on the shaft of the cylinder 5. The wheel 54 meshes with and drives a pinion 58 secured on the shaft of the cylinder 4. Integral spur wheels 56, 57 are slidable on a short revoluble shaft 57^a. The wheel 56 meshes with and is driven by the broad-faced wheel 45'.

When the parts are in the position shown in Fig. 18 the wheel 57 meshes with the wheel 54 and drives the cylinders 5 and 4 at half-speed, and when the wheel 56 is slid outward and secured in proper position, the wheel 56 meshing with the pinion 55 will drive the cylinders 5 and 4 at full-speed. The vertical shaft 42 rotates at full-speed and through the instrumentality of the gears 44, 45, 49, 48 and 50 drives the cylinders 6 and 7 at full-speed; and in like manner the shaft 42' through the instrumentality of the gears 44', 45', 49', 48', 50', 51 and 52 drives the cylinders 6', 7', 64^a and 64 at full-speed. The wheel 49 is slidable on its spindle 49^a and may be pulled to place in disuse the left hand cutting and collecting unit, and the wheel 49' is slidable on its spindle 49^{a'} and may be pulled to place the right hand main cutting and collecting unit in disuse.

In practice webs from both sections of the machine may be led to one section to be operated upon by the cutting, collecting and folder devices of that section of the machine, but in that case all the webs from both sections of the machine must be controlled just the same as if all the main cutting, collecting and folder devices were in use, and in order that all the webs may be properly controlled, it is desirable that the web-propelling and slitting devices 24, 24^a, 24', 24^{a'}, etc., remain always in operation. To accomplish this result the web-propelling devices are actuated by the intermediate wheels 47 and 47' driven by the wheels 45 and 45' respectively; but the wheels 45 and 45' also drive the cutting and collecting units by means of the intermediate wheels 49 and 49', it is obvious therefore that if the wheel 49 (or 49' as the case may be) be pulled, the cutting and collecting unit actuated by that wheel will stop, but the web-propelling devices will continue in operation.

If it be desired to operate the printing mechanisms and the cutting and collecting mechanisms of the left hand section of the apparatus and place the cutting and collecting mechanisms of the right hand section in disuse, it will only be necessary to slide the

- wheel 35' on the shaft 40' to place it out of mesh with the driving wheel 33; and if it be desired to place the cutting and collecting mechanisms of the left hand section in disuse it will only be necessary to pull the wheel 35 out of mesh with the drive wheel 34. The tapes 14, 15 and 16 (Figs. 1 and 4) run around and are actuated by the cylinder 64, and the tapes 14', 15' and 16' run around 10 and are actuated by the cylinder 64^a. Bevel cog wheels 60 and 60' (Fig. 16) secured on the shafts 40 and 40' drive bevel cog pinions 63 and 63' secured on the horizontal revolute counter shafts 59 and 59' respectively. 15 Spur wheels 62 and 62^a are connected with the shafts of the cylinders 19 and 19^a, and similar spur wheels 62' and 62^a' are connected with the shafts of the cylinders 19' and 19^a' respectively. A spur wheel 61^x 20 (Fig. 2) on the shaft 59, and an intermediate gear 62^x, coöperate to drive the train actuating the cylinders 19 and 19^a; and a spur wheel 61^x' on the shaft 59' and an intermediate gear 62^x' coöperate to drive the train 25 actuating the cylinders 19' and 19^a.

Switches above the formers.—Adjustable switches shown in detail in Figs. 12-15, co-operate with the cylinders 64 and 64^a (see also Figs. 38-40) to control the run of the 30 sheets from the main cutting and collecting units to the formers, or to the central delivery devices between the formers.

A stationary V-shaped guide 69^e substantially conforming to the curvature of the 35 cylinders 64 and 64^a has in its lower edge notches 69^e in which the points of the switch blades 69 pass each other. The switch blades 69 are mounted on shafts 69^d and are shaped to conform to the curvature of the 40 cylinders 64 and 64^a. When the upper ends of the adjacent switch blades are turned toward the cylinders the points of the blades will occupy the channels 64^b and serve to strip the sheets from the cylinder. The 45 blades 69 may be adjusted to cause the points of the blades to enter the channels 69^b or cause them to withdraw from the channels and occupy a position under the guide 69^e as shown in Figs. 4 and 12. When the blades 50 are adjusted in the desired position they may be secured by suitable securing devices 69^f.

Rotating delivery devices 67 (Figs. 1 and 4) of any usual construction are centrally located between the opposite pairs of 55 formers and under the switches. When the switch blades are set in the position shown in Fig. 13 the sheets from both cylinders 7 and 7' will pass between the cylinders 64 and 64^a and drop simultaneously onto the 60 delivery device 67. When the blades are set in the position shown in Fig. 14 the sheets from the cylinders 7 and 7' will run over the right hand switch blade 69 to the right hand formers 12' and 12^a'. When the blades 65 occupy the position shown in Fig. 15 the sheets

from the cylinder 7 will run on the left hand blade 69 to the left hand formers 12 and 12^a and the sheets from the cylinder 7' will run on the right hand blades 69 to the right hand formers 12' and 12^a'.

Assembling the sections.—The means for controlling and assembling the first-folded sheets or sections will now be described. Parallel rotative cylinders 64' and 64^a' (Figs. 5 and 6) similar to the cylinders 64 and 64^a are below and centrally located with respect to the pair of formers 12 and 12^a, and similar cylinders 64'' and 64^a'' are below and centrally located with respect to the formers 12' and 12^a'. Rotative rollers 17^x 75 are adjacent and parallel to the cylinders 64', 64^a' and carry tapes 16 running on the rollers 17, 17^x and 18. Rotative rollers 17^x' adjacent and parallel to the cylinders 64'' and 64^a'' carry tapes 16' running on the rollers 17', 17^x' and 18'. The rollers 17^x and 17^x' are mounted on arms 17^d supported on stationary shafts 17^e and secured by set screws 17^f. The rollers 18 and 18' are mounted on arms 18^d supported on stationary shafts 18^e and secured by set screws 18^f. By loosening the set screws the arms supporting the rollers 17^x, 17^x', 18 and 18' may be moved to adjust the rollers to tighten or loosen the tapes, and when the rollers are 85 properly adjusted the set screws may be tightened to hold the arms in place.

Switches below the formers.—The run of the first-folded sheets or sections from the cylinders 64', 64^a', 64'' and 64^a'' is controlled by means which will now be described. Upper switch blocks N¹ (Fig. 20) are secured on stationary horizontal shafts n⁷ and lower switch blocks N² are secured on oscillative shafts n⁸. The shafts n⁸ may be turned by the handles n⁹ and when placed in the desired position may be secured by the set screws n¹⁰. The curved surfaces n¹² and n¹³ of the blocks N¹ and N² respectively 100 conform to the circumferences of the assembling cylinders. In the lower ends of the blocks N¹ are notches n¹⁴. The upper ends n¹⁵ of the blocks N² traverse the notches n¹⁴ when the shafts n⁸ are turned. The cylinders 64', 64^a', 64'' and 64^a'' have circumferential channels 64^b in which the stripper-ends n¹⁶ of the blocks N² fit. If the shafts n⁸ be turned to the right the members n¹⁵ of the blocks N² will lie in the channels of the right hand cylinder and will serve to strip the sheets from that cylinder, and if the shafts n⁸ be turned to the left the members n¹⁵ will lie in the channels and strip the sheets, or sections, from the left hand cylinder. When the members n¹⁵ occupy 110 the notches n¹⁴ the sheets, or sections, running from the right hand assembling cylinder will run downward along the right hand curved surfaces n¹³ of the blocks N² to the right hand carrier cylinders; and sheets 115

running from the left-hand assembling cylinders will run downward along the left hand concave surfaces of the blocks N^2 , to the left hand carrier cylinders.

5 If it be desired to lead all the sheets, or sections, to the right it is only necessary to turn the shafts n^8 to the left to cause the parts n^{15} to strip the sheets from the left-hand assembling cylinders and lead them 6 downward to the right-hand carrier cylinders. To lead all the sheets to the left-hand carrier cylinders it is only necessary to turn the shafts n^8 to the right. To lead some sheets to the right and other sheets to the 15 left, some of the shafts n^8 will be turned to the left and others will be turned to the right, to control the sheets as already described.

Carrier cylinders, second-folders, etc.—

20 There are four single-width, full-speed rotary carrier cylinders 19, 19^a, 19', 19'' (Figs. 5, 6, and 41-43) below and in range with the lower edges of the formers 12, 12^a, 12' and 12'' respectively. The carrier cylinders 25 and appurtenances are all alike, so a description of one will suffice for all.

The cylinder 19—shown in detail in Figs. 41-43, is mounted to rotate in suitable bearings on the main frame. Folder blades M^4 of usual construction are mounted on shafts m which extend through the cylinder and rotate in suitable bearings in the cylinder. Cog pinions m^1 are secured on the shafts m . A stationary circular plate M^5 has a circular channel m^2 adapted to accommodate blocks m^3 connected with the shafts and traveling in the channel and has a toothed segment m^4 with which the pinions m^1 alternately mesh at one stage of the revolution 35 of the cylinder 19, and the pinions meshing with the teeth of the segments cause the blades M^4 to rotate and project the edges of the blades alternately outward through the openings m' in the wall of the cylinder, 40 each time that an opening m' is adjacent to the co-operating folder-rollers 20. Shafts M^6 extend through the cylinder 19 and oscillate on suitable bearings m^6 in the cylinder. Sets of pins m^7 of usual construction are 45 mounted on the shafts M^6 and are adapted to be projected through corresponding openings m^8 in the circumferential wall of the cylinder. Arms M^7 secured on the shafts M^6 respectively carry rollers m^9 which run 50 in contact with the peripheral surface of a stationary cam plate M^1 having its center in the extended axis of the cylinder and having an integral cam m^{10} . When the arms M^7 are properly adjusted on the shafts M^6 55 they will be secured by set screws m^{12} . The parts are so constructed and arranged that when the rollers m^9 run on the high part of the cam m^{10} the set of pins actuated by the arm M^7 on which the roller is mounted 60 will be retracted and the set of pins con-

trolled by the roller running on the low part of the cam will be projected. It will be seen therefore that during one complete rotation of the cylinder the sets of pins will be alternately effective and ineffective, and the pins will control the sheets, or sections, in a manner which is well known. Parallel rotating folder-rollers 20, 20^a, 20' and 20'' (Figs. 5 and 6) co-operate with the cylinders 19, 19^a, 19' and 19'' and are adapted to 70 make the second fold of sheets, or sections, running from the cylinders 64', 64^a, 64'' and 64'''', or either of them. Rotating delivery devices 67^t, 67^a, 67'' and 67''^a receive the second-folder papers folded by the respective sets of folder-rollers. If it be desired to drop the first-folded papers, or sections, onto the delivery devices 67^t, 67^a, 67'', 67''^a, the strippers N will be used to strip the first-folded sheets, or sections, from the cylinders and cause them to drop directly onto the delivery devices.

A set of combined strippers and shields N , shown in detail in Fig. 21 is mounted on an oscillative shaft n adjacent and parallel to the cylinder 19 and the folder-rollers 20. Similar sets of strippers and shields are adjacent and parallel to the other cylinders 19^a, 19' and 19'' respectively. The sets of strippers and shields are all alike so I will describe in detail only the set co-operating with the cylinder 19. The shaft n may be turned by a handle n' and when set in any desired position may be secured by the set screws n^2 . Cylindrical blocks n^5 eccentric to the shaft are mounted to slide and turn on the shaft, to facilitate adjustments of the blades N relative to each other and relative to the cylinder 19. When the blocks are 90 suitably placed on the shafts they will be secured by set screws n^6 . The blades N are mounted to turn on the blocks n^5 and may be secured in different positions by set screws n^4 . Strippers n^{17} integral with the blades N serve to strip the papers from the upper roller 20 and the creased sheets running between the rollers drop onto the delivery device 67^t.

If it be desired to drop the first-folded sheets running from the cylinder 19 onto the delivery device 67^t without making the second fold, the strippers N will be set in such position that the points of the strippers will strip the first-folded sheets from the cylinder 19 and they will run downward over the strippers and will drop onto the delivery device 67^t. The other sets of strippers and shields N are adapted to co-operate in the same manner with the cylinders 19^a, 19' and 19'' respectively.

Alternate run of one-leaf supplement sheets derived from a two-leaf secondary sheet of a composite web.— If a two-page-wide composite web comprising the matter of alternate two-leaf primary sheets and

two-leaf secondary sheets as shown in Fig. 24 be used, or if a composite web a plurality of pages in width and comprising the matter of alternate two-leaf primary sheets and 5 two-leaf secondary sheets on a two-page-wide member of the web as shown in Fig. 25 be used; it will be necessary to slit centrally each two-page-wide secondary sheet cut from the composite web, or web-member, 10 and comprising the matter of two one-leaf sheets, in order that one one-leaf supplement sheet may be inserted with one or more direct-running two-leaf main sheets, or with a plurality of collected main sheets, or with 15 a two-leaf primary sheet cut from the composite web, alone, or associated with two-leaf main sheets cut from the main web, or webs, or web-member. The sets of switches 69, 69', 69'' and 69''' (Fig. 38) may be set 20 to effect the proper run of the two-leaf primary sheet and the companion one-leaf supplement sheets derived from the two-leaf secondary sheet of the composite web. There are three secondary slitters 90, 90^a, and 90^b 25 (Figs. 6, 38-40) cutting on the cylinder 64 and three similar slitters 90', 90^{a'} and 90^{b'} cutting on the cylinder 64'. The slitters are adjustable so that any one or more of the slitters may be effective to slit the sheets at 30 the option of the user. The sets of switches are separately adjustable to admit of a number of different runs of the two-leaf primary sheets, or the one-leaf supplement sheets, derived from the two-leaf secondary sheets 35 of the composite web.

When a two-page-wide composite web, or web-member, is running with its median line in line with the noses of the opposite formers 12 and 12' and it is desired to run to the 40 former 12' the primary two-leaf sheet cut from the composite web and insert with it on the same former a one-leaf supplement sheet derived from the two-leaf secondary sheet of the composite web the two-leaf primary sheet will run to the cylinder 7' and 45 may be associated thereon with a main sheet, or sheets, or with collected main sheets running on the cylinder and upon being stripped therefrom by the strippers 80 the associated sheets including the one-leaf insert sheet will run downward over the former 50 12'. The secondary sheet cut from the composite web will run around the cylinder 7 to the cylinder 64 and will be slit centrally 55 thereon by the slitter 90.

The set of switches 69 will be set in the open position shown in Fig. 39 and the set of switches 69' will be set to lead the one-leaf sheets from the cylinder 64 to the 60 former 12' as indicated in Fig. 40. When the sets of switches 69 and 69' are set as described, one one-leaf supplement sheet will run between the switches 69 and drop onto the delivery device 67 and the companion 65 one-leaf sheet derived from the same two-

leaf secondary sheet will run over the set of switches 69' to the former 12' and will be inserted with the primary sheet or the associated primary sheet and main sheet, or sheets, running to the former.

Secondary cutter, operation.—If two-leaf insert sheets are cut by the secondary cutters 4 and 5 from a full-speed web, or webs, two pages in width, the two-leaf cuts will run alternately to opposite formers 12 and 12', or 12^a and 12^{a'}, as the case may be. If the web, or webs, are four pages in width a pair of two-leaf sheets will be cut from each web at each half revolution of the printing couples and the cuts will run alternately to 70 opposite pairs by side-by-side formers, that is to say, one cut comprising a pair of two-leaf sheets, or a plurality of pairs of two-leaf sheets will run to the side-by-side formers, 12 and 12^a and the next succeeding cut 75 comprising a pair, or a plurality of pairs of two-leaf sheets will run to the opposite pair of side-by-side formers 12' and 12^{a'}. The pairs of two-leaf insert sheets, cut by the secondary cutter, operating at full speed, 80 will be alternately associated with the two-leaf main sheets cut and collected by the main cutting and collecting units respectively, and two groups of associated sheets, including a two-leaf insert sheet in each 85 group, will respectively run over and be folded centrally on the side-by-side formers of one pair, and two groups of associated sheets, including a two-leaf insert sheet in each group will respectively run over and 90 be folded centrally on the side-by-side formers of the other pair. If a half-speed two-page-wide insert web is used the secondary cutter will operate at half-speed, and one main cutting and collecting unit will operate 95 at full speed, and all the cuts from the secondary cutter will be inserted with the collected main sheets running on the main cutting and collecting unit and all will be folded together as they run downward over one 100 former. If one or more four-page-wide main cutting and collecting unit will operate 105 at full speed, and all the cuts from the secondary cutter will be inserted with the collected main sheets running on the main cutting and collecting unit and all will be folded together as they run downward over one 110 former. If one or more four-page-wide main cutting and collecting cylinders 115 6, 7 and 6' 7' will be in use. The supplement web-member of the composite web will run to the cylinders 4 and 5 and will be cut thereby into one-leaf supplement sheets. The four-page-wide main webs slit to form 120 two-page-wide web members will run to the main cutting and collecting cylinders 6 and 7 and will be cut thereby into main sheets one page in length and two pages in width and the two-leaf main sheets will be collected. The first one-leaf supplement sheet 125 printed by plates occupying half the circumference of the supplement printing unit will run from the cylinders 4 and 5 to the cylinders 6 and 7 and will be inserted with the 130

two-leaf main sheets running thereon and the two-leaf main sheets, including the one-leaf supplement sheet, will run downward over the formers 12 and 12^a and will be folded centrally; the next succeeding one-leaf supplement sheet running from the cylinders 4 and 5 will run to the cylinders 6^a and 7^a, will be stripped from the cylinder 7^a by the strippers 80 and will run between the cylinders 6^a and 6^a¹ and fall onto the central delivery device 67. The one-leaf supplement sheets running from the cylinders 4 and 5 to the cylinders 6 and 7 are all printed by one set and invariably the same set of plates occupying one-half-circumference of the supplement plate cylinders and are invariably inserted with main pages printed by one set, and invariably the same set of main plates, and the one-leaf sheets running to the central delivery device invariably run from the other half-circumference of the supplement printing unit. In the present case the supplement printing unit comprises co-operating plate cylinders and impression cylinders, the plate cylinders being equipped with plates one page in width and extending around the circumference of the plate cylinders a distance equal to the length of two pages. The supplement printing area may be on plate cylinders independent of the main plate area, if a one-page-wide supplement web is used; or may be on the same cylinders with the main plate area if a composite web is used. Ordinarily and preferably the main printing area and the supplement printing area will operate at the same surface speed, but in exceptional cases herein set forth, the supplement plate area will operate at half-speed and the main plate area at full-speed.

Products.—An apparatus equipped with side-by-side formers, supplement cutters above the formers and main cutters and collectors above the formers and with one deck of the printing machine operating on one full-speed web can produce, with one set of plates for each product, page-for-plate papers as follows: (a) Two eight-page papers, each paper comprising two four-page sheets collected above the former and folded together in the first fold. (b) A ten-page paper in sections comprising two four-page sheets collected above one former and one two-page sheet running on the other former, the sheets being assembled below the formers and folded together in the second fold. (c) One twelve-page paper in two sections, one section comprising two four-page sheets, collected and folded together in the first fold and the other section comprising one four-page first-folded sheet, the sections being assembled below the formers and folded together in the second fold. (d) One fourteen-page paper in sections, one section comprising two four-page sheets collected above

the former, and the other section comprising a four-page sheet and a two-page sheet associated above the former and the sections assembled below the formers and folded together in the second fold. (e) One sixteen-page paper comprising two first-folded sections assembled below the formers and folded together in the second fold, each section comprising two four-page sheets collected before making the first fold, as shown in Fig. 30.

From the foregoing it will be seen that the apparatus is adapted to produce from one full-speed web running on one deck a ten-page paper from one set and the same set of plates at each revolution of the plate cylinders, or to produce from one full-speed web running on one deck, a fourteen-page paper from one set and the same set of plates at each revolution of the plate cylinders. Prior to my invention neither of these products have been produced by means of one set and the same set of plates for each product, operating on one full-speed web running on one deck, to perfect a complete paper at each revolution of the plate cylinders. In addition to the ten-page product and the fourteen-page product my machine can produce with one set of plates for each product all the other page-for-plate products just described.

Under the various conditions of operation all the supplement sheets running at full-speed to any given former are printed on both sides by one set and the same set of plates at each revolution of the plate cylinders, and the one-leaf sheets printed by that set of plates invariably run to the same former, for example: if the supplement sheets run only to the former 12 all the supplement sheets inserted with the main sheets running to that former will be printed by one set and the same set of plates. If opposite formers 12 and 12^a are used, the one-leaf supplement sheet printed by one set of plates will run to the former 12 and the one-leaf supplement sheet printed by the other set of supplement plates will run to the former 12^a. This run of the supplement sheets is distinguished from the prior art in that under the former practice duplicate plates, that is to say, two plates of a kind, were used on each supplement plate cylinder and the supplement web run at half-speed, so that if one one-leaf supplement sheet running to one former was printed by one set of plates the next succeeding one-leaf sheet running to the same former would be printed by another set of plates. My invention contemplates the use of a full-speed supplement web or web-member and all the one-leaf supplement sheets derived therefrom and running to one former are invariably printed on both sides by the same two supplement plates. The distinction is that under the

old method a half-speed supplement web is used, and four plates, two of which are duplicates, are used to print both sides of one one-leaf, two-page supplement sheet; 5 whereas, under my method the supplement web, or web-member, runs at full-speed and one plate prints one side of the one-leaf supplement sheet, and another plate prints the other side of the same supplement sheet and 10 two plates are never used to print one side of one one-leaf, two-page, supplement sheet running to any given former.

Some typical products and the mode of operating to produce them will now be described. Fig. 26 shows a one-page-wide supplement web running to the central cutter and a two-page-wide main web running to one of the main cutting and collecting devices. In this view the run of the supplement web 20 and supplement sheets are indicated by arrows terminated by a circle and the run of the main web and main sheets is indicated by arrows terminated by X. The main web is cut into two-leaf main sheets 25 by the cylinders 6 and 7 and the two-leaf main sheets are collected on the cylinder 6 and run downward over the former 12^a. The one-leaf supplement web is cut into one-leaf supplement sheets by the cylinders 30 4 and 5 and the one-leaf supplement sheets run alternately to the left-hand and the right-hand main cutting and collecting units. The one-leaf supplement sheet running to the cylinders 6 and 7 is inserted 35 with the two-leaf main sheets running thereon and runs downward over the former 12^a and is folded with the two-leaf sheets. The one-leaf supplement sheet running to the cylinders 6' and 7' runs thence between the 40 cylinders 64 and 64^a and drops onto the central delivery device 67. The product will be a ten-page-paper printed by one set and the same set of ten plates for each revolution of the plate cylinders.

45 Fig. 27 shows a four-page-wide composite web slitted centrally on the roller 24^a by the slitter 24, to divide the web into a two-page-wide main web-member and a two-page-wide supplement web-member comprising the matter of primary two-leaf insert sheets indicated by arrows terminated by X and secondary two-leaf sheets indicated by arrows terminated by circles. The main two-page-wide web-member of the 55 composite web runs to the left-hand main cutting and collecting cylinders 6 and 7 and is cut into two-leaf sheets and the sheets are collected and run downward over the former 12^a. The two-page-wide supplement web- 60 member runs to the central cutter cylinders 4 and 5 and is cut into sheets one-page-long and two pages wide. The two-leaf primary insert sheets run to the cylinders 6 and 7 and thence downward along the former 12. 65 The two-leaf secondary insert sheets run

between the cylinders 6' and 7' to the cylinders 64 and 64^a respectively. The slitter 9^a slits each secondary insert sheet centrally to divide it into two one-page-wide supplement sheets. One one-leaf supplement sheet runs 70 upward to and between the cylinders 6 and 7 and is inserted with the primary sheet running thereto from the cylinders 4 and 5 and the other one-leaf supplement sheet runs between the cylinders 64 and 64^a and 75 drops onto the central delivery device 67. The first-folded sections running from the formers 12 and 12^a are assembled between the rollers 64' and 64'^a to form a fourteen-page paper printed by one set and the same 80 set of fourteen plates at each revolution of the plate cylinders and comprising an eight-page section and a six-page section. The assembled sections may be folded together in the second fold by the folder rollers 20. 85

Fig. 28 shows a two-page-wide main web and a two-page-wide composite web. The composite web runs to the central cutters 4 and 5. The main web runs to the left-hand cutting and collecting cylinders 6 and 7 and is cut into two-leaf main sheets and the two-leaf sheets are collected. The cylinders 4 and 5 cut the composite web into two-leaf sheets running alternately to the right and left. One two-leaf sheet cut from the supplement web runs to the cylinders 6 and 7 and is inserted with the two-leaf main sheets cut and collected thereon. The other two-leaf sheet cut from the composite web runs around the cylinder 7' to the cylinders 100 64 and 64^a and is slitted centrally by the slitter 9^a. One one-leaf member of the two-leaf sheet runs from the cylinders 64 and 64^a upward to and around the cylinder 7 and is inserted with the two-leaf sheets running thereon. The other one-leaf member of the same two-leaf supplement sheet runs between the cylinders 64 and 64^a and drops onto the central delivery device 67. The 105 collected sheets including the inserts run from the cylinders 6 and 7 downward along the former 12 and are folded centrally thereon to produce a fourteen-page paper printed by one set and the same set of fourteen plates at each revolution of the plate cylinders. 110

Fig. 29 shows two associated two-page-wide main webs running to the left-hand cutting and collecting cylinders 6 and 7 and cut into two-leaf sheets and the sheets collected. The collected sheets run downward over the former 12 and are folded centrally thereon to produce a sixteen-page book-form paper printed by one set and the same set of sixteen plates at each revolution of the 125 plate cylinders.

Fig. 30 shows a four-page-wide main web running on the roller 24^a and slitted centrally by the slitter 24. The two-page-wide main web-members run to the left-hand 130

main cutting and collecting cylinders 6 and 7 and are cut thereby into two-leaf sheets and the sheets collected and the collected sheets run downward over the formers 12 and 12^a and the first-folded sections are assembled between the cylinders 64' and 64^a to form a sixteen-page paper comprising two eight-page sections printed by one set and the same set of sixteen plates at each revolution of the plate cylinders. The assembled sections may be folded together in the second fold by the folder rollers 20. The two-page-wide web-members may run between the left-hand cutting and collecting cylinders 6' and 7' as indicated by arrow Z and the cut and collected sheets will then be folded on the formers 12' and 12^a.

Fig. 31 shows a two-page-wide main web running to the left-hand main cutting and collecting unit and a two-page-wide secondary web running to the central cutters 4 and 5. The main web running to the cylinders 6 and 7 is cut into two-leaf sheets and the sheets collected. The secondary web running to the cylinders 4 and 5 is cut into two-leaf sheets which run alternately to the left-hand main cutting and collecting unit and the right-hand main cutting and collecting unit. The sheets running to the cylinders 6 and 7 are inserted with the collected sheets running over the former 12 to form a first-folded twelve-page paper in book-form printed by one set and the same set of twelve plates at each revolution of the plate cylinders. The first-folded twelve-page paper may run around the cylinder 19 and the second fold will be made by the folder roller 20. The two-leaf secondary sheet running to the cylinders 6' and 7' will run thence between the cylinders 64 and 64^a and will drop onto the delivery device 67.

Fig. 32 shows a three-page-wide composite web and a two-page-wide main web. The supplement web-member of the composite web is in line with one row of pages of the main web. The composite web is slit by the slitter 24 to form a one-page-wide supplement web-member. The main web and the two-page-wide member of the composite web run to the cutting and collecting cylinders 6 and 7 and are cut into sheets one page in length and two pages in width and the sheets are collected. The one-page-wide supplement web-member of the composite web runs between the cylinders 4 and 5 and is cut into one-leaf supplement sheets which run alternately to the right and left. One one-leaf supplement sheet is inserted with the two-leaf main sheets collected on the cylinders 6 and 7 and the other one-leaf supplement sheet runs around the cylinder 7', between the cylinders 64 and 64^a and drops onto the central delivery device 67. The collected sheets from the cylinders 6 and 7 run downward along the formers 12 and 12^a and

are folded centrally thereon. The first folded sections are assembled between the cylinders 64' and 64^a, to form an eighteen-page paper printed by one set and the same set of eighteen plates at each revolution of the plate cylinders and comprising an eight-page section and a ten-page section. The assembled sections may run around the cylinder 19 and be folded together in the second fold by the folder rollers 20.

Fig. 33 shows a one-page-wide web associated with a two-page-wide web and running to the cutting and collecting cylinders 6 and 7 which cut the webs into two-leaf sheets and collect the sheets and the collected sheets run downward along the former 12 and are folded together to produce a book-form paper of twelve pages printed by one set and the same set of twelve plates at each revolution of the plate cylinders.

Fig. 34 shows a four-page-wide main web slit centrally by the slitter 24 to divide the web into two two-page-wide web-members running to the main cutting and collecting cylinders 6 and 7; and a four-page-wide composite web slit centrally by the slitter 24, to divide the composite web into two two-page-wide web-members, viz: one primary two-page-wide web member comprising the matter of two-leaf main sheets exclusively, and one secondary two-page-wide web-member comprising the matter of alternate two-leaf main sheets and two-leaf supplement sheets. It is obvious that both webs may run over the roller 24^a, as indicated by the dotted line Z^a and may be simultaneously slit by the slitter 24. The primary member of the composite web runs to the cylinders 6 and 7 and is associated with the main web running thereto. The four-page-wide main web and the two-page-wide primary web-member running to the cylinders 6 and 7 will be cut into sheets one page long and two pages wide and the sheets will be collected. The secondary member of the composite web runs to the cylinders 4 and 5 and is cut into sheets one page long and two pages wide. The first cut running from the cylinders 4 and 5 will comprise one two-leaf four-page main sheet and will run to the left hand cylinders 6 and 7 and will be associated with the two-leaf main sheets running thereon; the second cut will comprise a two-leaf supplement sheet and will run to the right hand cylinders 6' and 7', and so on in succession. The two-leaf supplement sheet will run around the cylinder 7' to the cylinder 64^a and be slit thereon by the slitter 9^a to divide the two-leaf supplement sheet into two one-leaf sheets; one one-leaf supplement sheet will run between the cylinders 64 and 64^a to the cylinder 7 and be inserted with the main sheets running thereon; and the other one-leaf sheet will run between the cylinders 64 and 64^a and drop onto the central delivery device 67.

Fig. 35 shows a one-page-wide web associated with a two-page-wide web and running to the cutting and collecting cylinders 6 and 7 which cut the webs into two-leaf sheets and collect the sheets and the collected sheets run downward along the former 12 and are folded together to produce a book-form paper of twelve pages printed by one set and the same set of twelve plates at each revolution of the plate cylinders.

device 67. The sheets running from the cylinders 6 and 7 including the one-leaf supplement sheet will run to and be folded on the formers 12 and 12^a. A fourteen-page section comprising three four page main sheets and a two-page insert sheet will run over and be folded on the former 12; and a sixteen-page section comprising four four-page sheets will run over and be folded on the former 12^a. The product will be a thirty-page paper printed from one set and the same set of thirty plates at each revolution of the plate cylinders and comprising a sixteen-page section folded on the former 12^a and a fourteen-page section folded on the former 12. The first-folded sections may be assembled between the cylinders 6^a and 64^a and run around the cylinder 19 and be folded together in the second fold by the folder rollers 20.

Fig. 35 shows a four-page-wide main web running on the roller 24^c and a three-page-wide composite web running on the roller 24^a. The slitter 24^y slits the main web centrally to form two two-page-wide main web-members running to the cylinders 6 and 7. The slitter 24 slits the composite web to form a one-page-wide supplement web-member in line with one row of pages of the main web and running to the cylinders 4 and 5 and a two-page-wide web-member running to the cylinders 6 and 7. It is obvious that both webs may run on the roller 24^a as indicated by the dotted line Z² and may be slit simultaneously by the slitter 24. The main web and the two-page-wide member of the composite web running to the cylinders 6 and 7 will be cut into sheets one page long and two pages wide, and the sheets collected, and the collected two-leaf main sheets will run to and be folded on the formers 12 and 12^a. The cylinders 4 and 5 cut the one-page-wide supplement web-member into sheets one page long and one page wide. The one-leaf sheets from the secondary cutter run alternately left and right to the cylinders 6 and 7, and the cylinders 6' and 7'. The one-leaf sheet running from the cylinders 4 and 5 to the cylinders 6' and 7' will run around the cylinder 7' and between the cylinders 64 and 64^a and will drop onto the delivery device 67. The product will be a twenty-six page paper printed by one set, and the same set of twenty-six plates at each revolution of the plate cylinders, and comprising a sixteen-page section folded on the former 12^a and a ten-page section including a two-page supplement, folded on the former 12. The sections may be assembled between the cylinders 6^a and 64^a and run around the cylinder 19 and be folded together in the second fold by the folder rollers 20.

The essence of the invention consists in the combination of the recited elements in an

apparatus adapted to produce any number of pages, within the capacity of the printing machine, without skipping any product, having a number of pages which is a multiple of two; and to produce any product having a number of pages which is a multiple of two but not a multiple of four, by means of a less number of printing couples than have heretofore been used to produce the same product. The main cutter operates at full speed and the secondary cutter is operable at full speed or optionally at half speed. If the full plate-capacity of the machine is sixteen pages the apparatus will print and fold six pages from six plates, eight pages from eight plates, ten pages from ten plates, when the supplement cutting devices and the main cutting devices are running at full speed; and if the product is a ten page paper a one-leaf two-page sheet will be discarded. Under another mode of operation of the same apparatus, ten pages will be produced from twelve plates, with the main cutter operating at full speed and the secondary cutter operating at half speed. Under another mode of operation, the product will be a twelve page paper printed by twelve plates and comprising two sixes collected on the main cutter. Under another mode of operation, the product will be a twelve page paper printed by sixteen plates; the main cutter running at full-speed and the secondary cutter at half-speed. Under another mode of operation, the product will be a fourteen page paper printed by fourteen plates, both the main cutter and the supplement cutter running at full speed, and discarding a one-leaf two-page sheet. Under another mode of operation, the product will be a sixteen page paper printed by sixteen plates; the web being cut into sheets by the main cutter and the sheets collected on the main cutter.

Having fully described my invention what I claim as new and desire to procure by Letters Patent is:

1. The combination of printing couples two pages in circumference and a plurality of pages in width and equipped with plates having columns circumferential to the plate cylinders and adapted to perfect both sides of two-page-wide main webs or web-members and a one-page-wide supplement web or web-member; opposite full-speed main cutters adapted to cut the plural-page-wide main webs or web-members into sheets one page long and two pages wide; opposite two-page-wide formers adjacent to said main cutters respectively and equipped with means for propelling cut sheets downward along said formers; a full-speed secondary cutter intermediately located relative to said main cutters and adapted to make one cut for each half-revolution of the supplement plate area to cut the supplement web or web-

- member into one-leaf sheets; and means for leading the cuts from said secondary cutter alternately to said two opposite formers, the cuts running to one former and inserted with the main sheets running thereon being invariably printed by plates occupying one half-circumference of the supplement plate area and the cuts running to the opposite former being invariably printed by plates occupying the other half-circumference of the supplement plate area. 2. The combination of printing couples two pages in circumference and a plurality of pages in width and equipped with plates having columns circumferential to the plate cylinders and adapted to perfect both sides of two-page-wide main webs or web-members and a one-page-wide supplement web or web-member; opposite full-speed main cutting and collecting devices adapted to cut plural-page-wide main webs or web-members into sheets one page long and two pages wide and collect said sheets; opposite two-page-wide formers adjacent to said main cutters respectively and equipped with means for propelling the collected sheets downward along said formers; a full-speed secondary cutter located to coöperate with said main cutting and collecting devices and adapted to make one cut for each half-revolution of the supplement plate area to cut the supplement web or web-member into one-leaf sheets; and means for leading the cuts from said secondary cutter alternately at full-speed to two opposite formers, the cuts running to one former and timed for insertion with the collected main sheets running thereon being invariably printed by plates occupying one half-circumference of the supplement plate area and the cuts running to the opposite former being invariably printed by plates occupying the other half-circumference of the supplement plate area. 3. The combination of printing couples two pages in circumference and a plurality of pages in width and equipped with plates having columns circumferential to the plate cylinders and adapted to perfect both sides of two-page-wide main webs or web-members and a one-page-wide supplement web or web-member; opposite full-speed main cutting and collecting devices adapted to cut plural-page-wide main webs or web-members into sheets one page long and two pages wide and collect said sheets; opposite pairs of two-page-wide formers adjacent to said main cutters respectively and equipped with means for propelling the collected sheets downward along said formers; a full-speed secondary cutter located to coöperate with said main cutting and collecting devices and adapted to make one cut for each half-revolution of the supplement plate area to cut the supplement web or web-member into one-leaf sheets; and means for leading the cuts from said secondary cutter alternately at full-speed to two opposite formers, the cuts running to one former and timed for insertion with the collected main sheets running thereon being invariably printed by plates occupying one half-circumference of the supplement plate area and the cuts running to the opposite former being invariably printed by plates occupying the other half-circumference of the supplement plate area; means for assembling the sections receiving the first fold on a plurality of side by side formers and means for folding the assembled sections together in the second fold. 5. The combination of printing couples two pages in circumference and two pages or a multiple of two pages in width and equipped with plates having columns circumferential to the plate cylinders and adapted to perfect both sides of two wide main webs or web-members and a two-page-wide secondary web or web-member; means for slitting the webs to form two-page-wide web-members; a full-speed main cutter adapted to cut the main webs or web-members into sheets one page long and two pages wide; two-page-wide side-by-side formers adjacent to the main cutter and equipped with means for propelling cut

sheets downward along said formers; a full-speed secondary cutter adapted to make one cut for each half-revolution of the plate cylinders to cut the two-page-wide secondary web or web-member into sheets one-page-long and two pages wide; a delivery device adapted to receive cuts running from said secondary cutter and means for leading the cuts from said secondary cutter alternately at full-speed in opposite directions, one cut going to one former of the side-by-side formers and the next succeeding cut going to the delivery device, the two-page-wide and one-page-long web areas running from one half-circumference of the cylinders operating on the two-page-wide secondary web, or web-member constituting the cuts which always go to the former, and the two-page-wide web areas running from the other half-circumference of the same cylinders constituting the cuts which go to the delivery device.

6. The combination of printing couples two pages in circumference and two pages or a multiple of two pages in width and equipped with plates having columns adapted to perfect both sides of two-page-wide main webs or web-members and a two-page-wide secondary web or web-member; means for slitting the webs to form two-page-wide web-members; a full-speed main cutter adapted to cut the main webs or web-members into sheets one page long and two pages wide; two side-by-side formers adjacent to the main cutter and equipped with means for propelling the cut sheets downward along the formers; a full-speed secondary cutter adapted to make one cut for each half-revolution of the plate cylinders to cut the two-page-wide secondary web or web-member into sheets one page long and two pages wide; a delivery device adapted to receive cuts running from said secondary cutter; means for leading the cuts from the secondary cutter alternately at full-speed in opposite directions, one cut going to one former of the side-by-side formers and the next succeeding cut going to the delivery device; means for assembling the first-folded sections running from the side-by-side formers and a second folder adapted to fold together the assembled first-folded sections.

7. The combination of printing couples two pages in circumference and a plurality of pages in width and equipped with plates having columns circumferential to the plate cylinders and adapted to perfect the matter of main pages on both sides of one or more main webs and the matter of main pages and supplement pages on both sides of a composite web; means for slitting the webs to divide the composite web into a one-page-wide supplement web-member and a two-page-wide main web-member and to di-

vide the main web or webs into two-page-wide main web-members; a full-speed secondary cutter making one cut for each half-revolution of the plate cylinders to cut the two-page-wide member and the one-page-wide member of the composite web into sheets one page in length; means for leading the composite web to the secondary cutter; two main cutting and collecting devices adapted to cut the main webs or web-members into sheets one page long and two pages wide and collect the sheets; opposite pairs of side-by-side formers positioned to coöperate with the respective cutting and collecting devices; leaders adapted to lead cuts from the secondary cutter alternately to the opposite formers in position to be folded on the formers with the main sheets cut and collected by the respective cutting and collecting devices; two opposite second folders respectively located between two side-by-side formers; means for leading to one second folder the first-folded sheets running from two side-by-side formers; and means for leading to the other second folder first-folded sheets running from the other pair of side-by-side formers.

8. The combination of printing couples two pages in circumference and a plurality of pages in width and adapted to perfect both sides of two-page-wide webs or web-members running in parallel alinement face-to-face; a full-speed secondary cutter in line with the aligned face-to-face webs or web-members and adapted to make one cut for each half-revolution of the plate cylinders; means for leading one two-page-wide web or web-member to the secondary cutter; means for leading other two-page-wide aligned webs or web-members to main cutting and collecting devices; opposite main cutting and collecting devices positioned to coöperate with the secondary cutter; two-page-wide formers positioned to coöperate with the respective cutting and collecting devices; and leaders adapted to lead cuts from the secondary cutter alternately to the opposite formers in position for insertion with collected two-leaf sheets running on the formers respectively, the cut running from the secondary cutter to one former being invariably printed by plates occupying one half-circumference of the plate cylinders and the cut running to the opposite former being invariably printed by plates occupying the other half-circumference of the same plate cylinders.

9. The combination of printing couples two pages in circumference and a plurality of pages in width and adapted to perfect both sides of two-page-wide webs, or web-members, running in parallel alinement face-to-face; a full-speed secondary cutter in line with the aligned face-to-face webs or web-members and adapted to make one cut

- for each half-revolution of the plate cylinders; means for leading one two-page-wide web or web-member to the secondary cutter; means for leading the other two-page-wide 5 aligned webs or web-members to a main cutting and collecting device; a full-speed main cutting and collecting device in line with the face-to-face webs or web-members and adapted to make one cut for each half-revolution of the plate cylinders and collect a plurality of sheets for each complete revolution of the plate cylinders; a two-page-wide former adjacent to the main cutting and collecting device; a delivery device positioned to coöperate with the secondary cutter; leaders adapted to lead one cut from the secondary cutter to the former and the next succeeding cut to the delivery device, the cuts going from the secondary cutter to 10 the former always running from one half-circumference of the plate cylinders and the cuts going to the delivery device always running from the other half-circumference of the same plate cylinders.
- 25 10. The combination of printing couples two pages in circumference and a plurality of pages in width and equipped with plates having columns circumferential to the plate cylinders and adapted to perfect the matter 30 of main pages on both sides of one or more main webs and the matter of main pages and supplement pages on both sides of a composite web; means for slitting the webs to divide the composite web into a one page wide supplement web-member and a two-page-wide main web-member and to divide the main web or webs into two-page-wide main web-members; a full-speed secondary cutter making one cut for each 35 half-revolution of the plate cylinders perfecting the composite web to cut the two-page-wide member thereof into two-leaf sheets one page in length and to cut the one-page-wide member thereof into one-leaf sheets one page in length, the sheets cut off at one cut always running from one half-circumference of the cylinders perfecting the composite web and the sheets cut off at the next succeeding cut always running 40 from the other half-circumference of the same cylinders; a delivery device positioned to receive alternate cuts running from the secondary cutter; a main cutting and collecting device adapted to cut the main web or webs into sheets one page long and two pages wide and collect the sheets; side-by-side formers adjacent to and coöperating with the main cutting and collecting device; leaders leading cuts from the secondary cutter alternately to the delivery device and the side-by-side formers, the sheets running to the formers being timed for insertion with collected sheets running on the formers; and means for assembling the first-folded sections running from the side-by-side formers 45 and a second folder adapted to fold the sections together in the second fold.
11. The combination of printing couples comprising plate cylinders two pages in circumference and a plurality of pages in width and equipped with plates having columns circumferential to the plate cylinders and adapted to perfect the matter of two-leaf main sheets on both sides of one or more main webs or web-members and the matter 50 of two-leaf primary sheets and two-leaf secondary sheets on both sides of a two-page-wide secondary web or web-member; means for slitting the webs into two-page-wide web-members; opposite main cutting 55 and collecting devices adapted to cut the main webs or web-members into sheets one-page-long and two pages wide and collect the sheets; a secondary cutter intermediate of the main cutting and collecting devices 60 and adapted to cut a primary sheet one page long and two pages wide and a secondary sheet one page long and two pages wide at each revolution of the plate cylinders, the primary sheet comprising four main pages 65 on the two sides thereof and the secondary sheet comprising supplement pages on the two sides thereof; leading devices adapted to lead the cuts from the secondary cutter alternately at full-speed to the opposite 70 main cutting and collecting devices; stripers adapted to strip sheets from the main cutting and collecting devices; a plurality of side-by-side formers adjacent to one cutting and collecting device and equipped with means for propelling sheets downward along the formers and adapted to fold centrally two-leaf sheets cut and collected by 75 said cutting and collecting device; a slitter adjacent to the other cutting and collecting device and adapted to slit centrally the two-leaf secondary sheets running from the secondary cutter to said last named cutting and collecting device and comprising the matter 80 of supplement pages to divide said sheets into one-leaf sheets; a delivery device adjacent to said slitters and a switch adapted to guide one of said one-leaf sheets comprising the matter of supplement pages to one former in position for insertion with the two-leaf main sheets and the two-leaf primary sheet running thereon and to guide the companion one-leaf sheet to said delivery device.
12. The combination of printing couples comprising plate cylinders a plurality of pages in width and two pages in circumference and equipped with plates having columns circumferential to the plate cylinders and adapted to perfect on both sides of one or more main webs the matter of two-leaf main sheets and to perfect on both sides of a secondary web or web-member the matter 90 of two-leaf primary sheets and two leaf secondary sheets comprising the matter of sup-

plement pages; opposite main cutting and collecting devices adapted to cut the main web, or webs into sheets the full-width of the web and one page in length and collect the sheets; a full-speed secondary cutter making one cut for each half-revolution of the plate cylinders to cut the secondary web into primary sheets one page long and two pages wide and secondary sheets one page long and two pages wide and comprising the matter of supplement pages; leaders adapted to lead cuts from the secondary cutter alternately at full-speed to the opposite main cutting and collecting devices, the primary sheets all going to one cutting and collecting device and the secondary sheets all going to the other cutting and collecting device; slitters adjacent to the respective cutting and collecting devices and adapted to slit the cut and collected full-width main sheets to form sub-sheets one page long and two pages wide and likewise adapted to slit the two-page-wide secondary sheets to divide them into sub-sheets one page long and one page wide; a plurality of two-page-wide formers adjacent to the respective cutting and collecting devices and equipped with means to propel sheets downward over the formers; switches adjacent to the formers and the slitters and adjustable to send a one-leaf sub-sheet of one secondary sheet to one former and the companion sub-sheet of the same secondary sheet to the delivery device and a delivery device adapted to receive sheets from either cutting and collecting device.

13. The combination of printing couples comprising plate cylinders two pages or a multiple of two pages in width and two pages in circumference and equipped with plates having columns circumferential to the plate cylinders and adapted to perfect continuously moving webs two pages or a multiple of two pages in width; formers positioned to fold centrally lengthwise two-page-wide sheets derived from said webs or web-members; full-speed main cutters adapted to make one cut for each half-revolution of the plate cylinders; slitters between the printing means and the main cutters and adapted to slit the webs before cutting; and slitters between the main cutters and the formers and adapted to slit the main sheets after cutting and before folding.

14. The combination of printing couples comprising plate cylinders two pages in circumference and a plurality of pages in width and equipped with plates having columns circumferential to the plate cylinders and adapted to perfect the matter of two-leaf main sheets on both sides of one or more main webs or web-members and the matter of two-leaf main sheets and two-leaf secondary sheets on both sides of a two-page-

wide secondary web or web-member; means for slitting the webs into two-page-wide web-members; opposite main cutting and collecting devices adapted to cut the main webs or web-members into sheets one-page-long and two pages wide and collect the sheets; a secondary cutter intermediate of the main cutting and collecting devices and adapted to cut a primary sheet one page long and two pages wide and a secondary sheet one page long and two pages wide at each revolution of the plate cylinders, the primary sheet comprising four main pages on the two sides thereof and the secondary sheet comprising supplement pages on the two sides thereof; leading devices adapted to lead the cuts from the secondary cutter alternately at full-speed to the opposite main cutting and collecting devices; stripers adapted to strip sheets from the main cutting and collecting device; a plurality of side-by-side formers adjacent to one cutting and collecting device and equipped with means for propelling sheets downward along the formers and adapted to fold centrally two-leaf sheets cut and collected by said cutting and collecting device; a slitter adjacent to the other cutting and collecting device and adapted to slit centrally the two-leaf secondary sheets running from the secondary cutter to said last named cutting and collecting device and comprising the matter of supplement pages, to divide said sheets into two one-leaf sheets; a switch adapted to guide one of said one-leaf sheets comprising the matter of supplement pages to one former in position for insertion with the two-leaf main sheets running thereon and to guide the companion one-leaf sheet to said delivery device; means for assembling the first-folded sections running from the side-by-side formers including in one section a one-leaf supplement sheet derived from the two-leaf secondary sheet; and a second folder adapted to fold together the assembled sections.

15. The combination of printing means comprising plate cylinders two pages in circumference and a plurality of pages in width and equipped with plates having columns circumferential to the plate cylinders; a full-speed main cutter making two cuts for each revolution of the plate cylinders; a full-speed supplement cutter making two cuts for each revolution of the plate cylinders; means for leading the supplement cuts alternately in opposite directions; and a former positioned to fold centrally the two-leaf main sheets cut by the main cutter including a one-leaf insert sheet cut by the supplement cutter, the main cuts and the supplement cuts running to said former being invariably printed by one set and the same set of plates.

16. The combination of printing means

comprising plate cylinders two pages in circumference and a plurality of pages in width and equipped with plates having columns circumferential to the plate cylinders;

5 a full-speed main cutter making two cuts for each revolution of the plate cylinders; a full-speed supplement cutter making two cuts for each revolution of the plate cylinders; means for leading the supplement

10 cuts alternately in opposite directions; and a plurality of formers positioned to fold centrally the two-leaf sheets cut by the main cutter, including one-leaf insert sheets cut by the supplement cutter, the main cuts and

15 the supplement cuts running to any given former being invariably printed by one set and the same set of plates.

17. The combination of full-speed printing units two pages in circumference and

20 equipped with plates having columns circumferential to the plate cylinders; a full speed secondary cutter making two cuts for each revolution of the plate cylinders; means for leading the cuts from the sec-

25 ondary cutter in the first instance alternately in opposite directions, slitters and switches positioned to coöperate with the secondary cutter; means for leading the cuts from the secondary cutter convergently

30 toward said slitters and switches; a delivery device positioned to coöperate with said switches and slitters; and a former, or formers, positioned to coöperate with said slitters, switches and delivery device.

35 18. The combination of printing means comprising plate cylinders two pages in circumference and a plurality of pages in width and equipped with plates having col-

40 umns circumferential to the plate cylinders; a full-speed main cutting and collecting unit making two cuts for each revolution of the plate cylinders; a full-speed supplement cutter making two cuts for each revolution

45 of the plate cylinders; a former positioned to fold centrally two-leaf main sheets cut and collected by the main cutting and collecting unit including a one-leaf insert sheet cut by the supplement cutter, the main cuts and the supplement cuts running to said

50 former being printed by one set and the same set of plates; a delivery device back of the former; and means for leading cuts from the supplement cutter alternately to the main cutting and collecting unit and the

55 delivery device, the mechanisms being so arranged that the supplement cut going to the main cutting and collecting unit will run from one half-circumference of the supplement plate cylinders and the cut going to the delivery device will run from the other half-

60 circumference of the same plate cylinders.

19. The combination of full speed rotat-

ing printing couples a plurality of pages in width and two pages in circumference and

65 equipped with plates having columns cir-

cumferential to the plate cylinders and adapted to perfect both sides of a two-page-wide composite web; a full speed cutter making two cuts for each revolution of the printing couples to cut the composite web into alternate primary and secondary sheets one page in length and two pages in width; a slitter adapted to slit centrally every secondary two-leaf sheet, to divide it into two one-leaf sheets; means for propelling to said slitter every secondary two-leaf sheet, always printed by the same plate surface occupying one half-circumference of the plate cylinders; means for associating with the primary sheet one one-leaf sheet derived from the secondary two-leaf sheet and means for discarding the other one-leaf sheet derived from the secondary two-leaf sheet.

17. The combination of full-speed rotat-

ing printing couples a plurality of pages in width and two pages in circumference, and equipped with plates having columns circumferential to the plate cylinders and adapted to print on both sides of a two-

page-wide web; a full speed cutter making two cuts for each revolution of the printing

85 couples to cut the web into alternate primary and secondary sheets one page in length and two pages in width; a slitter adapted to slit centrally every secondary

50 two-leaf sheet to divide it into two one-leaf sheets; means for associating one one-leaf sheet with each two-leaf primary sheet;

55 and a former adapted to fold centrally the two-leaf sheet with the inserted one-leaf sheet.

21. The combination of full-speed rotat-

ing printing couples two pages in width and two pages in circumference, and equipped with plates having columns circumferential to the plate cylinders and adapted to print on both sides of a two-page-wide web; a

105 full speed cutter making two cuts for each revolution of the printing couples to cut the web into alternate primary and sec-

110 ondary sheets one page in length and two pages in width; a slitter adapted to slit centrally every secondary two-leaf sheet to di-

115 vide it into two one-leaf sheets; means for associating one one-leaf sheet with each two-

leaf primary sheet and discarding the other one-leaf sheet; a former adapted to fold cen-

120 trally the primary two-leaf sheet with the one-leaf insert sheet; and a delivery device positioned to receive the discarded one-leaf sheet.

22. In combination with full-speed rotat-

ing printing couples, adapted to print on both sides of a two-page-wide web; a full-speed cutter making two cuts at each

125 revolution of the printing couples to cut the web into alternate two-leaf primary sheets and two-leaf secondary sheets; means for

130 leading the cuts alternately in opposite directions; a folder adapted to fold the pri-

- mary sheet centrally; a slitter adapted to slit each secondary two-leaf sheet to form two one-leaf sheets; means for discarding one one-leaf sheet; and means for leading the companion one-leaf sheet to the folder.
23. In combination with full-speed rotating printing couples, adapted to print on both sides of a two-page-wide web; a full speed cutter making two cuts at each revolution of the printing couples to cut the web into alternate two-leaf primary sheets and two-leaf secondary sheets; means for leading the cuts alternately in opposite directions; a folder adapted to fold the primary sheets centrally; a slitter adapted to slit each secondary two-leaf sheet to form two one-leaf sheets; and means for leading the one-leaf sheets alternately in opposite directions and inserting one one-leaf sheet with each two-leaf primary sheet.
24. In combination with full-speed rotating printing couples, adapted to print on both sides of a two-page-wide web; a full speed cutter making two cuts at each revolution of the printing couples to cut the web into alternate two-leaf primary sheets and two-leaf secondary sheets; means for leading the cuts alternately in opposite directions; a slitter adapted to slit each secondary two-leaf sheet to form two one-leaf sheets; means for leading the one-leaf sheets alternately in opposite directions and inserting one one-leaf sheet with each two-leaf primary sheet; and means for folding centrally the two-leaf sheets.
25. The combination of full speed printing couples two pages in width and two pages in circumference and equipped with plates having columns circumferential to the plate cylinders and adapted to print a two-page-wide main web and a two-page-wide composite web; a full-speed main cutting and collecting unit adapted to make two cuts at each revolution of the printing couples to cut the main web into two-leaf sheets one page in length and two pages in width and collect the sheets; a full speed secondary cutter adapted to make two cuts for each revolution of the printing couples to cut the composite web into alternate primary and secondary two-leaf sheets; a slitter adapted to slit centrally every secondary two-leaf sheet to form two one-leaf sheets; a delivery device positioned to receive one-leaf sheets running from said slitter; means for inserting with the collected two-leaf main sheets a two-leaf primary sheet running from said secondary cutter and a one-leaf sheet running from said slitter; and means for leading the other one-leaf sheet from the slitter to the delivery device.
26. The combination of full-speed printing couples two pages in width and two pages in circumference and equipped with plates having columns circumferential to the plate cylinders and adapted to print on both sides of a composite web and both sides of a plurality of two-page-wide webs; op-
- the plate cylinders and adapted to print a two-page-wide main web and a two-page-wide composite web; a full-speed main cutting and collecting unit adapted to make two cuts at each revolution of the printing couples to cut the main web into two-leaf sheets one page in length and two pages in width and collect the sheets; a full-speed secondary cutter adapted to make two cuts for each revolution of the printing couples to cut the composite web into alternate primary and secondary two-leaf sheets; a slitter adapted to slit centrally every secondary two-leaf sheet to form two one-leaf sheets; a delivery device positioned to receive one-leaf sheets running from said slitter; means for inserting with the collected two-leaf main sheets a two-leaf primary sheet running from said secondary cutter and a one-leaf sheet running from said slitter; means for leading the other one-leaf sheet from the slitter to the delivery device; and a former adapted to fold centrally the associated and collected two-leaf main sheets and the inserted two-leaf primary sheet, including a one-leaf insert sheet.
27. The combination of full-speed printing couples two pages in width and two pages in circumference and equipped with plates having columns circumferential to the plate cylinders and adapted to print a plurality of two-page-wide main webs and a two-page-wide composite web; means for associating the main webs; a full-speed main cutting and collecting unit adapted to make two cuts at each revolution of the printing couples to cut the associated main webs into two-leaf sheets one page in length and two pages in width and collect the sheets; a full-speed secondary cutter adapted to make two cuts for each revolution of the printing couples to cut the composite web into alternate primary and secondary two-leaf sheets; a slitter adapted to slit centrally every secondary two-leaf sheet to form two one-leaf sheets; a delivery device positioned to receive one-leaf sheets running from said slitter; means for inserting with the associated and collected two-leaf main sheets a two-leaf primary sheet running from said secondary cutter, and one one-leaf sheet running from said slitter; means for leading the other one-leaf sheet from the slitter to the delivery device; and a former adapted to fold centrally the associated and collected two-leaf main sheets and the inserted two-leaf primary sheet, including a one-leaf insert sheet.
28. The combination of full-speed printing couples two pages in circumference and two pages in width and equipped with plates having columns circumferential to the plate cylinders and adapted to print on both sides of a composite web and both sides of a plurality of two-page-wide webs; op-

posite full-speed main cutting and collecting units adapted to make two cuts at each revolution of the printing couples, to cut a main web, or webs, into two-leaf sheets one page in length and two pages in width and collect the sheets; means for leading a main web, or webs, to the respective opposite cutting and collecting units; means for leading one web to a secondary cutter; a full-speed 5 secondary cutter adapted to make two cuts for each revolution of the printing couples, to cut the web running thereon into alternate primary and secondary two-leaf sheets; opposite formers positioned to coöperate 10 with the respective main cutting and collecting units; and means for inserting with the collected main sheets running to one former, the primary two-leaf sheets running from the secondary cutter and inserting 15 with the collected main sheets running to the opposite former, the two-leaf secondary sheets running from the secondary cutter.

29. The combination of full-speed printing couples two pages in circumference and two pages in width and equipped with plates having columns circumferential to the plate cylinders and adapted to print on both sides of a two-page-wide composite web and both 25 sides of a plurality of two-page-wide main webs; opposite full-speed main cutting and collecting units adapted to make two cuts at each revolution of the printing couples, to cut a main web, or webs, into two-leaf sheets 30 one page in length and two pages in width and collect the sheets; means for leading a main web, or webs, to the respective opposite cutting and collecting units; means for leading the composite web to the secondary cutter; a full-speed secondary cutter adapted 35 to make two cuts for each revolution of the printing couples, to cut the composite web into alternate primary and secondary two-leaf sheets; opposite formers positioned to coöperate with the respective main cutting and collecting units; a slitter adapted to slit centrally each two-leaf secondary sheet to divide it into two one-leaf sheets; a delivery device positioned to receive one-leaf sheets 40 running from said slitter; means for inserting with the collected main sheets running to one former a primary two-leaf sheet running from the secondary cutter and one one-leaf sheet running from the slitter; and means for leading to the delivery device the other one-leaf sheet running from the slitter.

30. The combination of full-speed printing couples two pages in circumference and two pages in width and equipped with plates 45 having columns circumferential to the plate cylinders and adapted to print on both sides of a one-page-wide supplement web and a plurality of two-page-wide main webs; opposite full-speed main cutting and collecting units adapted to make two cuts at each rev-

olution of the printing couples, to cut a main web, or webs, into two-leaf sheets one page in length and two pages in width and collect the sheets; means for leading a main web, or webs, to the respective opposite cutting and collecting units; a full-speed secondary cutter adapted to make two cuts for each revolution of the printing couples, to cut the supplement web into sheets one page in length and one page in width; opposite formers positioned to coöperate with the respective main cutting and collecting units; and means for leading one-leaf supplement sheets alternately to opposite formers and inserting them with the collected two-leaf sheets running on the formers respectively. 70

31. The combination of full-speed printing couples two pages in circumference and a multiple of two pages in width, and equipped with plates having columns circumferential to the plate cylinders, and adapted to print on both sides of a four-page-wide main web, or webs, and a four-page-wide composite web; means for slitting the webs to form two-page-wide web members; a full-speed main cutting and collecting unit adapted to make two cuts at each revolution of the printing couples to cut the main web, or webs, into two-leaf sheets one page in length and two pages in width and collect the sheets in two groups; a full-speed secondary cutter adapted to make two cuts for each revolution of the printing couples to cut the composite web into alternate primary and secondary two-leaf sheets; a secondary slitter adapted to slit centrally every secondary two-leaf sheet to form two one-leaf sheets; a delivery device positioned to receive one-leaf sheets running from the secondary slitter; means for inserting with each group of collected two-leaf main sheets a two-leaf primary sheet running from said secondary cutter and a one-leaf insert sheet running from the secondary slitter; and means for leading the other one-leaf sheets to the delivery device. 90

32. The combination of full-speed printing couples two pages in circumference and a multiple of two pages in width, and equipped with plates having columns circumferential to the plate cylinders, and adapted to print on both sides of a four-page-wide main web, or webs, and a four-page-wide composite web; primary slitters adapted to slit the web to form two-page-wide web-members; a full-speed main cutting and collecting unit adapted to make two cuts for each revolution of the printing couples to cut the main web, or webs, into two-leaf sheets one page in length and two pages in width and collect the sheets in two groups; a full-speed secondary cutter adapted to make two cuts for each revolution of the printing couples to cut each member of the composite web into alternate primary 105 110 115 120 125 130

and secondary two-leaf sheets; a secondary slitter adapted to slit centrally every secondary two-leaf sheet to form two one-leaf sheets; a delivery device positioned to receive one-leaf sheets running from the secondary slitter; means for inserting with the collected two-leaf main sheets of each group a two-leaf primary sheet running from said secondary cutter and a one-leaf insert sheet running from the secondary slitter; means for leading the other one-leaf sheets to the delivery device; and two side-by-side formers adapted to fold centrally the respective groups of collected two-leaf main sheets including a two-leaf insert sheet and a one-leaf insert sheet in each group.

33. The combination of full-speed printing couples two pages in circumference and a multiple of two pages in width and equipped with plates having columns circumferential to the plate cylinders and adapted to print on both sides of a plurality of four-page-wide main webs and a four-page-wide composite web; primary slitters adapted to slit the webs to form two-page-wide web-members; opposite full-speed main cutting and collecting units adapted to make two cuts for each revolution of the printing couples to cut the main webs into two-leaf sheets one page in length and two pages in width and collect the sheets in four groups; a full-speed secondary cutter adapted to make two cuts for each revolution of the printing couples to cut each member of the composite web into alternate primary and secondary two-leaf sheets; secondary slitters adapted to slit centrally the secondary two-leaf sheets to divide each two-leaf sheet into two one-leaf sheets; a delivery device positioned to receive one-leaf sheets running from said secondary slitters; means for inserting with the collected two-leaf main sheets of each of two groups a two-leaf primary sheet running from said secondary cutter and a one-leaf insert sheet running from a secondary slitter; means for leading the other one-leaf sheets to the delivery device; and opposite pairs of formers co-operating with the opposite main cutting and collecting units to simultaneously fold centrally the four groups of collected two-leaf sheets, including a two-leaf insert sheet and a one-leaf insert sheet in each of two groups.

34. The combination of full-speed printing couples two pages in circumference and a plurality of pages in width and equipped with plates having columns circumferential to the plate cylinders and adapted to print on both sides of a plurality of four-page-wide main webs and a two-page-wide supplement web; means for slitting the main webs into two-page-wide web-members; means for slitting the supplement web into one-page-wide web-members; opposite full-

speed main cutting and collecting units adapted to cut the two-page-wide web-members into sheets one page in length and two pages in width and collect the sheets in four groups; a full-speed secondary cutter adapted to cut the members of the supplement web into pairs of sheets each sheet being one page in length and one page in width; means for leading the supplement cuts alternately to opposite main cutting and collecting units and inserting them with the collected two-leaf sheets running on the respective main cutting and collecting units; and opposite pairs of formers respectively adjacent to the opposite main cutting and collecting units and adapted to fold simultaneously centrally the four groups of collected two-leaf sheets with a one-leaf insert sheet in each group.

35. The combination of full-speed rotating printing couples a plurality of pages in width, and two pages in circumference, and equipped with plates having columns circumferential to the plate cylinders and adapted to print on both sides of a two-page-wide web by means of one set, and the same set of plates, a complete paper including insert, for each revolution of the printing couples; a full-speed cutter making two cuts for each revolution of the printing couples to cut the web into alternate primary and secondary sheets one page in length and two pages in width; a slitter adapted to slit centrally every secondary two-leaf sheet to divide it into two one-leaf sheets; means for associating one one-leaf sheet with each two-leaf primary sheet and discarding the other one-leaf sheet; a former adapted to fold centrally the primary two-leaf sheet with the one-leaf insert sheet, all the pages running on the former being printed by one set, and the same set of plates; and a delivery device positioned to receive the discarded one-leaf sheet.

36. The combination of rotating printing couples a plurality of pages in width, two pages in circumference, and equipped with plates having columns circumferential to the plate cylinders, and adapted to print both sides of two four-page-wide main webs and one two-page-wide supplement web; means for slitting the main webs into two-page-wide web-members; means for slitting the supplement web into two one-page-wide web-members; opposite full-speed main cutting and collecting units adapted to cut the two-page-wide main web-members into sheets one page long and two pages wide and collect the sheets; means for leading a slit four-page-wide main web to each cutting and collecting unit; opposite pairs of formers positioned to co-operate with the opposite main cutting and collecting units; a full-speed secondary cutter making two cuts for each revolution of the printing couples to

cut the supplement web-members into sheets one page long and one page wide; and means for leading the cuts from the secondary cutter alternately to the opposite main cutting and collecting units and inserting them with the collected main sheets running thereon; to simultaneously produce four ten-page book-form papers with a two-leaf insert in each paper, by means of four sets of plates comprising ten plates in each set.

37. The combination of full-speed printing means comprising two rotative plate cylinders a plurality of pages in width, two pages in circumference and equipped with plates having columns circumferential to the plate cylinders; full-speed main cutting and collecting means making two cuts for each revolution of the plate cylinders; a full-speed secondary cutter making two cuts for each revolution of the plate cylinders; means for inserting sheets cut by the secondary cutter with sheets cut by the main cutting and collecting means, or sheets cut and collected by the main cutting and collecting means; and means for folding the sheets; said mechanisms being co-operative to print by means of one set of plates for each paper, and fold, a complete paper at each revolution of the plate cylinders, and effective to print by means of one set of plates for each product, and fold, any product within the capacity of the plate cylinders and comprising two pages, or any multiple of two pages, at the option of the operator.

38. The combination of printing means comprising two rotative plate cylinders a plurality of pages in width, two pages in circumference, and equipped with plates having columns circumferential to the plate cylinders; main cutting and collecting means making two one-page-long cuts for each paper; a secondary cutter cutting sheets one page in length; and means for inserting one secondary cut with the main sheets in each paper; said mechanisms being co-operative to print, cut and fold any product within the capacity of the plate cylinders and comprising two pages, or a multiple of two pages in each paper.

39. The combination of full speed rotative plate cylinders, a plurality of pages in width, two pages in circumference and equipped with a single set of plates for main pages and supplement pages and having columns circumferential to the plate cylinders; full-speed cutting means effective to make two cuts from the main web and two cuts from the supplement web at each revolution of the plate cylinders; means for collecting the main cuts; means for inserting in each paper one sheet cut from the supplement web and means for final disposal of the next succeeding sheet cut from the supplement web; all said mechanisms co-oper-

ating at full speed to print by means of one set of plates, cut and fold as one product at each revolution of the full speed plate cylinders equipped with main plates and supplement plates, book form papers comprising printed sheets exclusively and including one two-page insert sheet in each paper, said papers being of variable sizes beginning with ten pages and increasing by four pages for each size.

40. The combination of printing means comprising two full-speed plate cylinders a plurality of pages in width, two pages in circumference and equipped with a single set of main and supplement plates having columns circumferential to the plate cylinders and adapted to print both sides of a full-speed web; main cutting and collecting means adapted to cut from the web before folding two one-page-long cuts for each paper and collect the cuts; means for severing insert sheets one page in length and one page in width; means for inserting one insert sheet with the main sheets of each paper; and means for folding the cuts, including one two-page insert in each paper; said mechanisms being co-operative to print by means of a single set of plates at each revolution of the plate cylinders and cut and fold as one product, papers of variable sizes within the capacity of the plate cylinders, each paper consisting of two sections, one section having an insert sheet and the other section being without an insert sheet.

41. The combination of plate cylinders a plurality of pages in width, a plurality of pages in circumference and equipped with plates having columns circumferential to the plate cylinders; means for continuously propelling a plural-page-wide main-web and a plural-page-wide supplement web printed by said plate cylinders; means for cutting the main-web longitudinally and transversely to form one-page-long two-leaf sheets in rows; means for cutting the supplement-web longitudinally and transversely to form pairs of rows of one-page-long supplement sheets; means for propelling the supplement sheets of one row of a pair in one direction; means for propelling the supplement sheets of the complementary row of the same pair in the opposite direction; and means for associating the supplement sheets with the main sheets.

42. The combination of plate cylinders a plurality of pages in width, a plurality of pages in circumference and equipped with plates having columns circumferential to the plate cylinders; means for continuously propelling a plural-page-wide main web and a plural-page-wide supplement web; means for severing the main web to form one-page-long two-leaf sheets in rows; means for severing the supplement web longitudinally and transversely to form pairs of rows of

- one-page-long supplement sheets; means for propelling the supplement sheets of one row of a pair in the first instance in one direction; means for propelling supplement sheets of the complementary row of the same pair in the first instance in the opposite direction; and means for inserting one-leaf two-page supplement sheets with the main sheets.
43. The combination of means for continuously propelling a plural-plate-wide main web and a plural-plate-wide composite web; means for severing the main web to form two-leaf sheets in rows; means for severing the composite web to form two-leaf main sheets and pairs of one-leaf two-page supplement sheets; means for propelling one supplement sheet of a pair in one direction and the other supplement sheet of the same pair in the opposite direction; and means for associating the two-leaf main sheets with one one-leaf insert sheet in each paper.
44. The combination of plate cylinders a plurality of pages in width, a plurality of pages in circumference and equipped with plates having columns circumferential to the plate cylinders and adapted to print the matter of pages on both sides of a continuously moving web; means for propelling a perfected composite web comprising the matter of one-page-long two-leaf main sheets and pairs of one-page-long one-leaf sheets; means for severing the web to divide it into one-page-long two-leaf sheets and one-page-long one-leaf sheets; and means for associating a one-page-long one-leaf sheet with each one-page-long two-leaf main sheet.
45. The combination of plate cylinders a plurality of pages in width, a plurality of pages in circumference and equipped with plates having columns circumferential to the plate cylinders and adapted to print both sides of a continuously moving web; means for propelling a perfected composite web comprising the matter of one-page-long two-leaf main sheets and pairs of one-page-long one-leaf sheets perfected by a single set of plates; means for severing the web to divide it into one-page-long two-leaf sheets and one-page-long one-leaf sheets; and means for associating a one-page-long one-leaf sheet with each one-page-long two-leaf main sheet.
46. The combination of printing means comprising plate cylinders having effective printing surface two-pages in width and two pages in circumference and equipped with plates having columns circumferential to the plate cylinders and adapted to perfect on a continuously moving web the matter of two-leaf primary sheets and the matter of two-leaf secondary sheets; a full speed cutter making two cuts at each revolution of the plate cylinders to cut the web into primary sheets one page long and two pages wide and secondary sheets one page long and two pages wide and propel the primary sheet in one direction and the secondary sheet in the opposite direction; a former positioned to fold centrally the two-leaf primary sheets; means for slitting each secondary sheet to divide it into two one-leaf sheets; means for propelling one one-leaf sheet in one direction and the other one-leaf sheet in the opposite direction; and means for inserting one one-leaf sheet with each two-leaf primary sheet running to the former.
47. In an apparatus of the class described, the combination of full speed rotating printing couples, a plurality of pages in width and two pages in circumference and equipped with plates having columns circumferential to the plate cylinders and adapted to print both sides of a full speed two-page-wide web; a full speed cutter making two cuts for each revolution of the printing couples to cut the web into two-leaf sheets; a slitter positioned to slit centrally sheets cut by said cutter; and means for propelling from said cutter to said slitter, every second sheet cut by said cutter, the sheets going to said slitter being printed by plates occupying one and the same half-circumference of the plate cylinders.
48. The combination of printing couples having circumferential columns as described, with a full speed cutter making two cuts at each revolution of the printing couples to cut the web into sheets one page in length and two pages in width; a slitter positioned to slit the sheets cut by said cutter; and means for propelling to said slitter each second sheet cut by said cutter.
49. In an apparatus of the class described, the combination of full-speed main printing surface two pages in circumference and a plurality of pages in width and equipped with plates having columns circumferential to the plate cylinders and adapted to perfect both sides of a main web; half-speed secondary printing surface two pages in circumference and a plurality of pages in width and equipped with plates having columns circumferential to the plate cylinders and adapted to perfect both sides of a half-speed secondary web; a full-speed main cutter making two cuts at each revolution of the plate cylinders to cut the main web into main sheets one page long and two pages wide; a secondary cutter operating at half-speed to make two cuts at each revolution of the secondary plate cylinders to cut the secondary web into insert sheets one page long and two pages wide; and means for inserting the insert sheets with the main sheets.
50. The combination of plate cylinders two pages in circumference and equipped with plates having columns circumferential to the plate cylinders to cut the web into

to the plate cylinders and adapted to print the matter of main sheets, primary sheets and secondary sheets; means adapted to divide the web into main sheets, primary sheets and secondary sheets; means for collecting the main sheets; means for associating a primary sheet with the collected main sheets; means for dividing each secondary sheet into two sub-sheets; means for associating one sub-sheet with the primary sheet; means for final disposal of the other sub-sheet; and means for folding together two main sheets, one primary sheet, and one sub-sheet, to produce one complete fourteen page-paper printed by one and the same set of plates, at each revolution of the plate cylinders.

51. The combination of plate cylinders two pages in circumference and equipped with plates having columns circumferential to the plate cylinders and adapted to print the matter of main sheets, primary sheets, and secondary sheets; means adapted to divide the web into main sheets, primary sheets, and secondary sheets; means for collecting a plurality of main sheets; means for associating a primary sheet with the collected main sheets; means for dividing each secondary sheet into two sub-sheets; means for associating one sub-sheet with the primary sheet; means for final disposal of the other sub-sheet; and means for folding together a plurality of main sheets, one primary sheet and one sub-sheet to produce a complete paper printed by one and the same set of plates at each revolution of the plate cylinders and folded as a single product.

52. The combination of two full-speed plate cylinders two pages in circumference and a plurality of pages in width and equipped with plates having columns circumferential to the plate cylinders and adapted to print one side of a web on one plate cylinder and print the other side of the web on the other plate cylinder; and full-speed slitting, cutting, collecting and folding mechanisms in operative relation to the printing means and coöperating therewith to produce any size paper within the capacity of the printing machine, consisting of one paper folded as one product and having a number of pages which is a multiple of two, printed by a single set of plates, at each revolution of the plate cylinders.

53. The combination of full-speed plate cylinders two pages in circumference, a plurality of pages in width and equipped with plates having columns circumferential to the plate cylinders and adapted to print both sides of a web or webs; a main cutting and collecting device adapted to make two cuts at each revolution of the plate cylinders and collect the cuts; a secondary cutting device adapted to make two cuts for each revo-

lution of the plate cylinders; a former in operative relation to the main cutting and collecting device and adapted to fold main sheets including one insert sheet in each product; means for forwarding a main web or webs from the printing means to the main cutting device; means for forwarding a web or web-member from the printing means to the secondary cutting device; means for propelling the cuts from the secondary cutting device alternately in different directions; and means for controlling the cuts, one cut going in one direction to the main cutting and collecting device to be inserted with the main sheets and the other cut going in a different direction to the place of final disposal, all coöperating to produce one complete paper printed by a single set of plates and folded as one product at each revolution of the plate cylinders.

54. The combination of printing means comprising plate cylinders two pages in circumference, a plurality of pages in width and equipped with plates having columns circumferential to the plate cylinders and adapted to perfect a plurality of continuously moving webs; means for associating and forwarding all of the webs; two opposite folders in operative relation to the printing and forwarding means; a cutting device central with respect to the opposite folders and adapted to cut the webs into sheets one page in length; means for leading the perfected webs to said central cutting device; means for leading one cut to the right-hand folder; and means for leading the next succeeding cut to the left-hand folder, all the pages of the cuts running to one folder being printed by a single set of plates occupying one half-circumference of the plate cylinders and all the pages of the cuts running to the other folder being printed by a single set of plates occupying one half-circumference of the same plate cylinders.

55. The combination of plate cylinders equipped with plates having columns circumferential to the plate cylinders; a plurality of web-forwarding means; two opposite folders; a cutting device central with respect to the opposite folders and operable at full-speed or optionally at half-speed and having cutting means spaced to cut the web or webs into sheets the length of one page plus margins, also having sheet-holding means effective to carry the cuts alternately to both folders, or to carry all the cuts to one folder; and leaders controlling the cuts going to the folders.

56. The combination of plate cylinders equipped with plates having columns circumferential to the plate cylinders; a plurality of web-forwarding means; two opposite folders; a pair of cutting cylinders central with respect to the opposite folders and

having sheet-holding means and cutting means on each cylinder spaced apart the length of one page plus margins; strippers effective to strip the cuts from each cylinder; and means for controlling the alternate cuts running to two opposite folders.

57. The combination of plate cylinders equipped with plates having columns circumferential to the plate cylinders; a plurality of web-forwarding means; two rotary cutting cylinders each having sheet-holding means and a cutting device spaced apart the length of one page plus margins; strippers co-acting with each cylinder to strip the cuts from the cylinders; means for leading the cuts alternately from both cylinders; means for leading all the cuts from one cylinder in one direction; and means for controlling the stripped cuts.

58. The combination of plate cylinders equipped with plates having columns circumferential to the plate cylinders; a plurality of web-forwarding means; two rotary cutting cylinders in operative relation to the web-forwarding means, each cylinder having sheet-holding means and a cutting device spaced apart the length of one page plus margins; strippers adapted to strip the cuts from the cylinders; means for leading the stripped cuts alternately from both cylinders and controlling the stripped cuts.

59. The combination of plate cylinders equipped with plates having columns circumferential to the plate cylinders; a plurality of web-forwarding means; two rotary cutting cylinders positioned to coöperate with the web-forwarding means and each cylinder having sheet-holding means and a cutting device spaced apart the length of one page plus margins; strippers adapted to strip the cuts from said cylinders; means effective to lead the cuts alternately from both cylinders, and likewise effective to lead all the cuts in one direction on one cylinder; and means controlling the cuts.

60. The combination of plate cylinders equipped with plates having columns circumferential to the plate cylinders; a plurality of web-forwarding means; two rotary cutting cylinders positioned to coöperate with the web-forwarding means and each cylinder having sheet-holding means and a cutting device spaced apart the length of one page plus margins; strippers adapted to strip the cuts from the cylinders; means effective to lead the cuts alternately from both cylinders and likewise effective to lead all the cuts in one direction on one cylinder; and means for controlling and delivering the cuts.

61. The combination of printing means comprising plate cylinders two pages in circumference, a plurality of pages in width and equipped with plates having columns circumferential to the plate cylinders and

adapted to perfect a plurality of continuously moving webs; two rotary cutting cylinders and two opposite folding devices in operative relation to the printing means, the rotary cutting cylinders having on each cylinder sheet-holding means and a cutting device spaced apart the length of one page plus margins; means for forwarding the perfected webs to said rotary cutting cylinders; means for leading one cut on one cylinder; means for stripping the cuts from the cylinder; means for leading the next succeeding cut on the other rotary cutting cylinder; means for stripping the cuts from said last-named cylinder; means for leading the alternate cuts to a right-hand and a left-hand folder, the cuts running to the right-hand folder being printed by a single set of plates which occupy half the circumference of the plate cylinders, and the cuts running to the opposite folder being printed by a single set of plates occupying the other half circumference of the same plate cylinders.

62. The combination of plate cylinders two pages in circumference a plurality of pages in width and equipped with plates having columns circumferential to the plate cylinders; impression cylinders coöperating with the plate cylinders respectively to print both sides of a plurality of continuously moving webs; means for associating and forwarding all the printed webs; two central rotary cutter cylinders, each having sheet-holding means and a cutting device spaced apart the length of one page plus margins; two opposite folders in operative relation to the printing means and the cutting means; means for stripping the cuts from both cutter cylinders; and means for leading the cuts alternately to opposite folders, the cuts going to one folder being printed by a single set of plates occupying one half-circumference of the plate cylinders and the cuts going to the opposite folder being printed by a single set of plates occupying the other half-circumference of the same plate cylinders.

63. In an apparatus of the class described, means effective to produce one complete ten-page paper printed by a single set of ten plates and folded as one product at each revolution of the plate cylinders; comprising two plate cylinders two pages in circumference equipped with plates having columns circumferential to the plate cylinders; impression cylinders coöperating with the plate cylinders respectively to print one side of a three-page-wide web by means of plates on one plate cylinder and to print the reverse side of the same web by means of plates on the other plate cylinder; means for propelling the perfected web; means for slitting the web to form a one-page-wide web-member and a two-page-web-member; main cutting and collecting means posi-

tioned to coöperate with the printing means and adapted to cut and collect four-page main sheets; a secondary cutter positioned to coöperate with the printing means and 5 adapted to cut the one-page-wide web-member into two-page sheets; a former adapted to fold the cut and collected four-page main sheets, including a two-page insert sheet; a delivery device back of the former; means 10 for leading the two-page-wide web-member to the main cutting and collecting means; means for leading the one-page-wide web-member to the secondary cutter; means for propelling alternately in different directions 15 the one-leaf sheets cut by the secondary cutter, the one-leaf sheets running in one direction being folded with the main sheets and the sheets running in the other direction going to the delivery device; the mechanisms 20 being so constructed and arranged that the one-leaf sheets running to the main sheets will always run from one half-circumference of the cylinders carrying the supplement plates, and the sheets running 25 to the delivery device will always run from the other half-circumference of the same plate cylinders.

64. The combination of printing means comprising full-speed plate cylinders two pages 30 in circumference a plurality of pages in width and equipped with plates having columns circumferential to the plate cylinders and adapted to print the matter of main pages and supplement pages on both 35 sides of a continuously moving web, means for severing the web to form two-page sheets and four-page sheets, and means for assembling and folding the sheets, to produce at each revolution of the plate cylinders by 40 means of a single set and the same set of plates one complete paper folded as one product and comprising a plurality of four-page sheets and one two-page insert sheet.

65. The combination of two full-speed 45 plate cylinders two pages in circumference a plurality of pages in width and equipped with plates having columns circumferential to the plate cylinders and arranged to print one side of the web on one plate cylinder 50 and print the other side of the web on the other plate cylinder; means for severing the web to form four-page sheets and two-page sheets; and means for assembling and folding the sheets, to produce at each revolution 55 of the plate cylinders, one complete paper printed by one set and the same set of plates and comprising a plurality of four-page sheets and one two-page insert sheet folded together as one product.

66. The combination of full-speed printing means comprising a plurality of rotative plate cylinders a plurality of pages in width two pages in circumference and equipped with plates having columns circumferential to the plate cylinders and

adapted to print the matter on both sides of a plurality of continuously moving webs; means for severing the webs to form four-page sheets and two-page sheets; and means for assembling and folding the sheets, to 70 produce at each revolution of the plate cylinders by means of a single set and the same set of plates, one complete paper folded as one product and comprising a plurality of four-page sheets and one two-page sheet in 75 each paper.

67. The combination of a plurality of full-speed rotating plate cylinders a plurality of pages in width two pages in circumference and equipped with plates having 80 columns circumferential to the plate cylinders and adapted to print the matter of pages on both sides of a plurality of continuously moving webs; means for severing the webs to form four-page sheets; means for dividing some four-page sheets to form two-page sheets; means for associating with a plurality of four-page sheets one two-page sheet derived from a four-page sheet; means for final disposal of the other two-page 90 sheet; and means for folding the associated sheets to produce at each revolution of the plate cylinders one complete paper printed by one set and the same set of plates and folded as one product comprising a plurality of four-page sheets and one two-page 95 insert sheet.

68. The combination of full-speed printing means comprising two rotative plate cylinders a plurality of pages in width, two 100 pages in circumference and equipped with plates having columns circumferential to the plate cylinders and adapted to print the matter of both sides of a continuously moving web a plurality of pages in width, and means for dividing the web into sheets and associating and folding the sheets; all cooperating at full-speed to produce one complete paper printed by one set and the same 105 set of plates at each revolution of the plate cylinders and folded as one complete product for each revolution of the plate cylinders.

69. The combination of full-speed printing means comprising a plurality of rotative 115 plate cylinders a plurality of pages in width two pages in circumference and equipped with plates having columns circumferential to the plate cylinders and adapted to print both sides of a plurality of continuously 120 moving webs; and means for dividing the webs into sheets and associating and folding the sheets; all operating at full-speed to produce one complete paper printed by one set and the same set of plates at each revolution of the plate cylinders and folded as one complete product for each revolution of the 125 plate cylinders.

70. The combination of full-speed rotating plate cylinders a plurality of pages in width 130

two pages in circumference and equipped 5 with plates having columns circumferential to the plate cylinders and adapted to print on both sides of one two-page-wide web by means of one set and the same set of plates, the matter of a complete paper including an insert, for each revolution of the plate cylinders; a full-speed cutter making two cuts for each revolution of the plate cylinders to 10 cut the web into alternate primary and secondary sheets one page in length; a slitter adapted to slit centrally every secondary two-leaf sheet to divide it into two one-leaf sheets; means for associating one one-leaf sheet with each two-leaf primary sheet; means for final disposal of the other one-leaf sheet; and a former adapted to fold centrally the primary two-leaf sheet including the one-leaf insert sheet, all the pages running on the former being printed by one set 15 and the same set of plates.

71. The combination of full-speed rotating plate cylinders a plurality of pages in width two pages in circumference and 20 equipped with plates having columns circumferential to the plate cylinders and adapted to print on both sides of one two-page-wide web by means of one set and the same set of plates the matter of a complete 25 paper including an insert, for each revolution of the plate cylinders; a full-speed cutter making two cuts for each revolution of the plate cylinders to cut the web into alternate primary and secondary sheets one page 30 in length; a slitter adapted to slit centrally every secondary two-leaf sheet to divide it into two one-leaf sheets; means for associating one one-leaf sheet with each two-leaf primary sheet; means for final disposal of 35 the other one-leaf sheet; a former adapted to fold centrally the primary two-leaf sheet including the one-leaf insert sheet, all the pages running on the former being printed by one and the same set of plates; and a 40 second folder adapted to make the second fold of papers receiving the first fold on the former.

72. The combination of full-speed rotating plate cylinders a plurality of pages in 50 width two pages in circumference and equipped with plates having columns circumferential to the plate cylinders and adapted to print on both sides of one two-page-wide web by means of one set and the same set of plates, the matter of a complete 55 paper including an insert, for each revolution of the printing couples; a full-speed cutter making two cuts for each revolution of the printing couples to cut the web into 60 alternate primary and secondary sheets one page in length; a slitter adapted to slit centrally every secondary two-leaf sheet to divide it into two one-leaf sheets; means for associating one one-leaf sheet with each two-leaf primary sheet; means for final disposal 65

of the other one-leaf sheet; a former adapted to fold centrally the primary two-leaf sheet including the one-leaf insert sheet, all the pages running on the former being printed by one and the same set of plates; second 70 folder mechanism adapted to make the second fold of papers receiving the first fold on the former; and a delivery device adapted to receive the second folded papers.

73. In combination with plate cylinders a plurality of pages in width two pages in circumference and equipped with plates having columns circumferential to the plate cylinders and adapted to print both sides of a continuously moving web; means for slitting 80 the web and cutting it into sheets always one page in length; and a slitter adapted to slit one-page-long sheets.

74. The combination of printing means comprising two rotative plate cylinders a 85 plurality of pages in width two pages in circumference and equipped with plates having columns circumferential to the plate cylinders; main cutting and collecting means making two one-page-long cuts for each 90 paper; a secondary cutter cutting sheets one-page in length; and means for inserting one secondary cut with the main sheets in each paper; said mechanisms being co-operative to print, cut and fold book-form papers 95 of variable sizes including a two-page insert in each paper, the difference between the successive sizes being four pages.

75. The combination of printing means comprising two rotative plate cylinders a 100 plurality of pages in width, two pages in circumference and equipped with plates having columns circumferential to the plate cylinders; main cutting and collecting means making two one-page-long cuts for each 105 paper; a secondary cutter cutting sheets one-page in length; and means for inserting one secondary cut with the main sheets in each paper; said mechanisms being co-operative to print, cut, and fold any paper within the 110 capacity of the plate cylinders, each paper consisting of two sections and comprising one section having a two-page insert sheet and another section without any insert sheet 115 viz; papers of variable sizes including one two-page insert in each paper, the difference between the successive sizes being four pages.

76. The combination of full-speed plate cylinders a plurality of pages in width two pages in circumference and equipped with plates having columns circumferential to the plate cylinders; two co-operating full-speed cutter cylinders in operative relation to the printing means; means for forwarding the printed web, or webs, to the cutting cylinders; and sheet-holding devices on the cutting cylinders adapted to take and hold on one cylinder sheets printed by the plates occupying one half-circumference of the 120 125 130

plate cylinders and to take and hold on the other cutter cylinder sheets printed by plates occupying the other half-circumference of the same plate cylinders; and means for stripping the sheets from said cutter cylinders respectively.

77. The combination of half-speed plate cylinders a plurality of pages in width two pages in circumference and equipped with plates having columns circumferential to the plate cylinders; two coöperating half-speed cutter cylinders in operative relation to the printing means; means for forwarding the printed web to the cutting cylinders; and sheet-holding devices on the cutting cylinders adapted to take and hold on either cutter cylinder all the sheets printed by plates occupying the entire circumference of the plate cylinders to lead the sheets all in one direction; and strippers for stripping the sheets from the cutter cylinders.

78. The combination of full-speed plate cylinders a plurality of pages in width two pages in circumference and equipped with plates having columns circumferential to the plate cylinders; half-speed plate cylinders a plurality of pages in width two pages in circumference and equipped with plates having columns circumferential to the plate cylinders; a pair of coöperating cutter cylinders in operative relation to the plate cylinders; gears adapted to actuate said cutter cylinders at full-speed or optionally at half-speed; sheet-holding devices on said cutter cylinders adapted to take and hold sheets running on said cutter cylinders; means for stripping the sheets from the cutter cylinders; opposite folders positioned to coöperate with said cutter cylinders; and means for rendering effective the sheet-holding devices on said cutter cylinders when operating at full-speed to propel the cuts alternately from the cutter cylinders to the folders, the cuts going to one folder being printed by plates occupying one half-circumference of the plate cylinders and the cuts going to the other folder being printed by plates occupying the other half-circumference of the plate cylinders, and to render effective the sheet-holding devices of the cutter cylinders when operating at half-speed to forward all the cuts to either folder, said cuts being printed by plates occupying the entire circumference of the plate cylinders.

79. The combination of two plate cylinders two pages in circumference and equipped with plates having columns circumferential to the plate cylinders; impression cylinders coöperating with the plate cylinders respectively to print on both sides of a continuously moving web; means for rotating the plate cylinders and impression cylinders at full-speed or optionally at half-speed; means for forwarding the printed

web to the cutting cylinders; rotative cutting cylinders adapted to make two cuts at each revolution of the plate cylinders to cut the web into sheets one page in length; means for rotating the cutting cylinders at full-speed or optionally at half-speed; sheet-holding devices on the cutting cylinders adapted to take and hold sheets carried on said cutting cylinders; a folder positioned to coöperate with the cutting cylinders; a receiver positioned to receive cuts running from said cutting cylinders; and means controlling the sheet-holding devices on said cutting cylinders, to forward all the cuts in one direction to the folder when the plate cylinders and cutting cylinders are rotating at half-speed or optionally to forward the cuts alternately to the folder and the receiver when the plate cylinders and cutting cylinders are rotating at full-speed, the cuts running from either half circumference of the plate cylinders going to the folder and the cuts running from the other half-circumference of the same plate cylinders going to the receiver.

80. The combination of two full-speed main plate cylinders two pages in circumference, a plurality of pages in width and equipped with a single set of plates having columns circumferential to the plate cylinders and adapted to print both sides of a continuously moving main web; two secondary plate cylinders two pages in circumference and equipped with plates having columns circumferential to the plate cylinders and operable at full-speed or optionally at half-speed to print both sides of a continuously moving web; means for forwarding the main web to the main cutting and collecting device; a full-speed main cutting and collecting device adapted to make two one-page-long cuts for each revolution of the full-speed main plate cylinders and collect the cuts; secondary cutter cylinders operable at full-speed or optionally at half-speed and co-acting to make two cuts at each revolution of the secondary plate cylinders to cut the secondary web into one-page-long sheets; sheet-holding devices on said secondary cutter cylinders adapted to take and hold the cuts carried on said cylinders; a folder in operative relation to the main cutting and collecting device and the secondary cutter cylinders; a receiver positioned to receive cuts running from the secondary cutter cylinders; means for inserting one sheet running from the secondary cutter cylinders with the collected main sheets of each paper; means for forwarding the collected main sheets and insert sheets to the folder; and means controlling the sheet-holding devices on said secondary cutter cylinders to forward all the secondary cuts in one direction to the folder when the secondary plate cylinders and secondary cutter cylinders are

- operating at half-speed and to forward the cuts in different directions when the secondary plate cylinders and secondary cutter cylinders are operating at full-speed, the cuts running from either half-circumference of the secondary plate cylinders going to the folder and the cuts running from the other half-circumference of the same plate cylinders going to the receiver.
81. The combination of a plurality of full-speed main plate cylinders two pages in circumference a plurality of pages in width and equipped with a single set of plates having columns circumferential to the plate cylinders and adapted to print both sides of a plurality of continuously moving webs; secondary plate cylinders two pages in circumference and equipped with plates having columns circumferential to the plate cylinders and operable at full-speed or optionally at half-speed to print both sides of a continuously moving web; means for associating the main webs and forwarding them to the main cutting and collecting device; a full-speed main cutting and collecting device adapted to make two cuts at each revolution of the main plate cylinders to cut the associated main webs into sheets one page in length and collect the cuts; secondary cutter cylinders rotative at full-speed or optionally at half-speed and co-acting to make two cuts for each revolution of the secondary plate cylinders to cut the secondary web into sheets one page in length; sheet-holding devices on said secondary cutter cylinders adapted to take and hold the cuts carried on said cylinders; a folder in operative relation to the main cutting and collecting device and the secondary cutter cylinders; a receiver positioned to receive cuts running from the secondary cutter cylinders; means for inserting sheets running from the secondary cutter cylinders with the collected cuts running from the main cutting and collecting device; means for forwarding to the folder the collected main cuts including one insert for each paper; and means controlling the sheet-holding devices on said secondary cutter cylinders to forward all the secondary cuts in one direction to the folder when the secondary plate cylinders and secondary cutter cylinders are rotating at half-speed and to forward the secondary cuts in different directions when the secondary plate cylinders and secondary cutter cylinders are rotating at full-speed, the cuts running from either half-circumference of the secondary plate cylinders going to the folder and the cuts running from the other half-circumference of the same plate cylinders going to the receiver.
82. The combination of plate cylinders, equipped with plates having columns circumferential to the plate cylinders and adapted to print both sides of a plurality of continuously moving webs; web-forwarding means; two rotary cutter cylinders positioned to co-operate with the web-forwarding means, each cutter cylinder having sheet-holding means and a cutting device spaced apart a distance equal to the length of one page plus margins, and effective to lead the cuts alternately in different directions from the two cylinders, and likewise effective to lead all the cuts in one direction on one cylinder; and means for controlling the cuts.
83. The combination of plate cylinders equipped with plates having columns circumferential to the plate cylinders and adapted to print both sides of a plurality of continuously moving webs; two opposite folders; two rotary cutting cylinders in operative relation to the opposite folders, each cutting cylinder having sheet-holding means and a cutting device, spaced apart the length of one page plus margins; means for forwarding the printed webs or web-members, to the two rotary cutting cylinders; means effective to carry the cuts alternately, to both folders, or to carry all the cuts to one folder; and leaders controlling the cuts going to the folders.
84. The combination of full-speed plate cylinders two pages in circumference and arranged on two decks, the plate cylinders on one deck being adapted to print both sides of an inside web and the plate cylinders on the other deck being adapted to print both sides of an outside web; half-speed plate cylinders two pages in circumference, and adapted to print both sides of a half-speed web; a full-speed main cutter and carrier device, parallel to the said plate cylinders; a half-speed supplement cutter and carrier device parallel to the plate cylinders, and co-operating with the main cutter and carrier device; means for forwarding the inside main web, to the main cutter and carrier device, parallel to the said plate cylinders; a half-speed supplement cutter and carrier device parallel to the plate cylinders, and co-operating with the main cutter and carrier device; means for forwarding the outside main web, on the other side of the half-speed supplement cutting device to the same main carrier and cutting device; means for forwarding the half-speed web, between the outside and inside main webs, to the half-speed supplement cutting device; means for propelling half-speed supplement sheets downwardly between the inside and outside main webs; means for controlling the leading ends of the main webs and the leading end of the supplement sheet between the main webs on said main carrier and means for folding the main sheets including a two-page supplement sheet in each paper.
85. In an apparatus for printing and folding papers, the combination of full-speed main plate cylinders two pages in circumference and equipped with plates hav-

ing columns circumferential to the plate cylinders and adapted to print both sides of two main webs; half speed plate cylinders two pages in circumference having plates 5 with columns circumferential to the plate cylinders and adapted to print both sides of a half-speed supplement web; half-speed supplement cutter and carrier cylinders adapted to cut the supplement web into two- 10 page supplement sheets and carry the sheets; full-speed main cutter and carrier cylinders positioned to coöperate with the supplement cutter and carrier cylinders and adapted to cut the main webs into four-page main 15 sheets and carry said main sheets; means for forwarding one main web on one side of the supplement cutter and carrier cylinders to the main cutter and carrier cylinders; means for forwarding the other main web 20 on the other side of the supplement cutter and carrier cylinders to the main cutter and carrier cylinders; means for controlling the leading end of the supplement web between the main webs before cutting off the supplement 25 sheet; means for forwarding the main sheets; and a former adapted to make the first fold of the main sheets, including one two-page insert sheet in each paper.

86. In an apparatus for printing and folding papers, the combination of full speed 30 main plate cylinders two pages in circumference and adapted to print both sides of two main webs; half-speed plate cylinders two pages in circumference and adapted to print both sides of a half-speed supplement 35 web; half-speed supplement cutter and carrier cylinders adapted to cut the supplement web into two-page supplement sheets and carry the sheets; full-speed main cutter and carrier cylinders positioned to coöperate with the supplement cutter and carrier cylinders and adapted to cut the main webs into four-page main sheets and carry said main 40 sheets; means for forwarding one main web on one side of the supplement cutter and carrier cylinders to the main cutter and carrier cylinders; means for forwarding the other main web on the other side of the supplement cutter and carrier cylinders to 45 the main cutter and carrier cylinders; means for controlling the leading end of the supplement web between the main webs before cutting off the supplement sheet; a pasteur 50 adapted to apply paste on one main web; means for forwarding the main sheets; a former adapted to fold the main sheets, including one supplement sheet in each paper; a second folder below the former; and a delivery device at right angles to the main 55 cutter and carrier cylinders and adapted to deliver the second-folded product.

87. The combination of full-speed main printing units comprising plate cylinders two pages in circumference arranged on two 60 decks and having plates with columns cir- 65 cumferential to the plate cylinders, the printing units on one deck being adapted to perfect one main web, and the printing units on the other deck being adapted to perfect another main web; half speed printing units comprising plate cylinders two pages in circumference arranged on one 70 deck and having plates with columns circumferential to the plate cylinders and adapted to perfect a continuously moving supplement web,—all said main and supplement printing units being parallel to each other and said supplement printing units being in such position that the supplement web will run between the two main 75 webs; a full speed main cutter and a half-speed supplement cutter parallel to the printing units; means for forwarding one full-speed main web on one side of the supplement cutter to the main cutter; means for forwarding the other full-speed main web on the other side of the supplement cutter to the main cutter; means for forwarding the half-speed supplement web between the full-speed main webs to the half-speed 80 supplement cutter; means for forwarding the supplement pages in registry with main pages; and a former adapted to make the first fold of the main sheets, including a supplement in each paper.

88. The combination of a plurality of full-speed printing units comprising plate cylinders two pages in circumference, and half-speed printing units comprising plate cylinders two pages in circumference, all of said 95 printing units being parallel to each other; a full speed main cutter cylinder; a full speed main carrier cylinder; half-speed supplement cutter and carrier cylinders; sheet controlling means on the main carrier cylinder and the supplement carrying cylinder; means for forwarding one full-speed perfected main web on one side of the supplement cutter and carrier cylinders and another full speed perfected main web on the 100 other side of the supplement cutter and carrier cylinders to the main carrier cylinder; means for forwarding the half-speed perfected supplement web between the main webs to the supplement cutter and carrier 105 cylinders and disposing the supplement pages in registry with the main pages; a former and a rotary folder effective to make the first and second folds of the main sheets, including a one-leaf two-page insert sheet in 110 each paper; and means for delivering the folded product at right angles to the main cutter.

89. The combination of printing units comprising a plurality of plate cylinders 115 two pages in circumference having plates with columns circumferential to the plate cylinders, and adapted to perfect both sides of two full-speed main webs and one half-speed supplement web; a full-speed main cutter; 120

a full-speed main carrier; and a half-speed supplement cutter and carrier; all parallel to the printing units; two rotary rollers co-operating with the main carrier; a former 5 below said rollers and adapted to make the first fold of the main sheets; and tapes running between said rollers and downwardly along each side of the former, to control the downwardly running sheets during the making of the first fold.

90. The combination of a main cutter cylinder and a main carrier cylinder co-operating with each other; a half-speed supplement cutter cylinder and a half-speed supplement carrier cylinder co-operating with each other; sheet controlling devices on the main carrier cylinder and the supplement carrying cylinder; means for forwarding one full-speed perfected main web on one 20 side of the supplement cutter and carrier cylinders to the main cutter, and forwarding another full speed perfected main web on the other side of the supplement cutter and carrier cylinders to the same main cutter; means for forwarding a half-speed perfected supplement web between the main webs to the supplement cutter and carrier cylinders, and disposing the supplement 25 pages in registry with the main pages; a former and a rotary folder adapted to make the first and second folds of the main sheets including a two-page supplement sheet in each paper; and means for delivering the second-folded papers at right angles to the 30 main cutter.

91. The combination of full-speed printing mechanisms comprising plate cylinders two pages in circumference effective to print on both sides of a continuously moving web, 40 or webs, the matter of main pages and supplement pages; a main severing and collecting device adapted to cut the main web or web-member into two four-page main-sheets and collect the sheets; a severing device effective to cut the supplement web or web-member into sheets; means for forwarding the main web or web-member to the main severing device; means for forwarding the supplement web or web-member to the supplement 45 severing device; means for inserting with the collected main sheets the supplement sheets running from part of the supplement-plate area of the cylinders; a former and a rotary folder adapted to make the first and second folds of the collected 50 main sheets, including a two-page insert in

each paper; and means for discarding back of the former the sheets running from the part of the supplement-plate area complementary to said first named part of the supplement-plate area of said plate cylinders.

92. The combination of full-speed main printing units comprising plate cylinders two pages in circumference arranged on two decks, the printing units on one deck being 60 adapted to perfect one main web, and the printing units on the other deck being adapted to perfect another main web; half speed printing units comprising plate cylinders two pages in circumference arranged on one 65 deck and adapted to perfect a continuously moving supplement web,—all said main and supplement printing units being parallel to each other and said supplement printing units being in such position that the supplement web will run between the two main webs; a full speed main cutter and a half-speed supplement cutter parallel to the printing units; means for forwarding one full-speed main web on one side of the supplement cutter to the main cutter; means for forwarding the other full-speed main web on the other side of the supplement cutter to the main cutter; means for forwarding the half-speed supplement web between the full speed main webs to the half-speed supplement cutter; means for forwarding the supplement pages in registry with main pages; a former and a rotary folder making the first and second folds; 80 and a delivery device at right angles to the main cutter.

93. In an apparatus for printing and folding papers, the combination of a means for printing and forwarding a main web, 95 or web-member and a supplement web, or web-member; means for severing the supplement web or web-member to form secondary sheets; means for severing the main web or web-member into main sheets and 100 collecting the main sheets; means for associating with the main sheets some sheets derived from the supplement web; means for discarding other sheets derived from the supplement web; and a former adapted to 105 fold the main sheets, including in each paper a sheet, or sheets derived from the supplement web.

JOHN A. BOYCE.
